RECORD PUNCHING MACHINE

Clair D. Lake, Binghamton, and Francis E. Hamilton, Endicott, N. Y., assignors to International Business Machines Corporation, New York, N. Y., a corporation of New York

Application August 24, 1946, Serial No. 692,758

56 Claims. (Cl. 164—113)

1

This invention relates to card punching machines and particularly to the type in which card punching is controlled from a plurality of different sources utilized singly or in combination.

The main object of the invention is to devise a card punching machine which is controlled by a source which is set up under control of a keyboard prior to the punching operation, and wherein said source comprises a storage unit which can be retained set up for gang punching cards, may be cleared out or reset for individual cards, or which can be reset in selected columns to correct an error in a setup prior to card punching.

It is another object of the invention to coordinate a card punching machine of the rapid punching type with coordinated different sources of control which enables variable and commonly punched data to be punched on the card in such manner that rapid punching effected by the punching machine can be utilized efficiently to maintain a high card punching output.

Another object of the invention is to include, in the different sources of control for the punching mechanism, a keyboard-controlled storage unit, in which the variable and commonly punched data are set up before a card punching operation and a master card analyzing unit which represents data to be commonly punched on the series of cards.

A still further object of the invention is to devise a construction of a card punching machine with a visible reading station which enables written data on cards, such as inventory cards, to be read by the operator for setting up the storage unit to represent such data, which data is subsequently punched on the related inventory card, which operations are known as "dual card-operations."

A still further object of the invention is to devise a construction of a card punching machine which can be selectively arranged so that punching of each card under control of the storage unit which is set up anew for each card according to the information taken by the operator from a written data sheet, bill, etc., and not off the card to be punched can be initiated manually or automatically immediately upon setting up the last column of the storage unit. This mode of operation differs from the preceding since the visible station is not utilized because the operator gets the data from a written sheet, bill, etc., and not off the card to be punched.

A still further object of the invention is to devise a construction of a card punching machine

2

which can be selectively conditioned and arranged to effect "gang punching" i. e., to punch cards in succession automatically from the different sources of information, the storage unit, and/or a master card, and with high output in card punching.

A still further object of the invention is to incorporate, in said card punching machines, controls by means of which the machine can be 10 conditioned to effect card punching by (1) dual card-operations, (2) successive card punching, either automatic or manually initiated or (3) gang punching, whereby a single machine can be arranged to effect these three main types of 15 operation at the will of the operator, thereby enabling a single machine to selectively do the jobs previously possible only by a plurality of other machines.

The complete combination of apparatus which 20 makes up a complete machine consists primarily of four units: (1) punch unit; (2) storage unit; (3) master card unit; (4) keyboard. Each unit itself is devised to include features of invention 25 and are to be considered as objects of the invention as follows:

Punch unit.—To provide an automatic or manually initiated card feed which feeds cards from a supply magazine to a visible reading station to enable the card to be held stationary at such station so that transcribed data visible thereon 30 may be utilized by the operator for setting up the storage unit; an automatic or manually initiated card feed which feeds the card from the visible reading station to a punching position, 35 a card feed automatically operable with the operation of the punching mechanism to feed the card through the punching mechanism, to incorporate in the punching mechanism automatically operated aligning means which aligns the card 40 on all sides—top, bottom and sideways to insure that the card will pass through the punching mechanism with proper registration between the index point positions and the punches, and in correct punching time; to provide an improved 45 construction of punch and die assembly which oscillates back and forth and a reciprocating punch operating mechanism both timed with the feeding of the card, making it unnecessary to stop the card while being punched as in prior 50 card punching constructions; to provide an improved card feeding means which will feed the punched card sideways out of the punching mechanism and eject it from the back of the machine to the front so that stacked punched 55 cards are at an advantageous position and can

be easily taken from the storage hopper by the operator when facing the machine in operating position.

Storage unit.—To devise a construction wherein the setup can be controlled by a keyboard so that successive columns of the storage unit are set up to represent characters as the keys are operated or skipped over if such columns are retained set up, to enable a combinational setup in each column to represent either numerical or alphabetical characters; to devise the setup arrangement as a readout which enables, under control of said readout, electrical impulses to be transmitted which are timed in operation with the passage of the card past the punches to select them; to enable the concurrent reset of all orders at will, either automatically at the completion of card punching operations or by a key on the keyboard to correct an error, to provide an alternative reset of columns which is sectionalized in groups of five columns so that five columns which include the one in which an error is indicated may be cleared out at a time without affecting the setup in other orders; to include a control whereby certain columns which are set up under control of the keyboard will be retained set up to represent data to be commonly punched for gang punching; to provide such control by a card inserted in the storage unit and perforated to represent columns to be retained set up, to split such control on the card by perforations arranged in different rows so that the control of resetting may be made more selective and flexible by special keys on the keyboard, and to enable columns which are retained set up to be skipped over without requiring any key or manual operations to thus save the operator's time.

Master card unit.—To provide a simple construction of analyzing unit which enables master cards to be repeatedly analyzed so that data on the master card may select the card punches to punch the cards to represent the same data; to provide on the keyboard of the machine a control whereby the master card unit may be called into or out of operation at the will of the operator.

Keyboard unit.—To provide a keyboard which is easily operated and of the electrical control type and so coordinated with the storage unit that the mere depression of the keys will set up the columns of the storage unit successively; to include on the keyboard certain special keys such as Major, Intermediate, Minor, Select skip, Start and Stop, etc., all of which are within easy access of the operator for functional operations; and to further carry out the object of providing a machine capable of different modes of operation by including a series of electrical switches which control the operation and conditioning of the machine to selectively effect various types of card punching operations.

Other objects of the invention will be pointed out in the following description and claims and illustrated in the accompanying drawings, which disclose, by way of example, the principle of the invention and the best mode, which has been contemplated, of applying that principle.

In said drawings:

Fig. 34 is a sectional view taken on the line 34—34 of Fig. 17a.

Fig. 35 is a sectional view taken on the line 35—35 of Fig. 17a.

Fig. 36 is an end view of the keyboard and is taken on the line 36—36 of Fig. 17a.

Figs. 37a, 37b, 37c and 37d when assembled in this order constitute the wiring diagram of the complete machine.

General description

Punch unit.—The punching machine is of the rapid successive punching type attaining a higher speed than prior machines by punching the card horizontal row by horizontal row without stopping the card and to this end the cards are fed down vertically, the row of "9" index points leading. By a card picker mechanism of a conventional design and associated feeding rollers, a cyclic operation of this feeding mechanism will feed a card to the visible station and be held at such station so that transcribed information usually written on the card can be read by the operator, since the card is in full view by the operator as the latter faces the machine.

Cards are fed from the visible reading station to a punching station so that the cards will come to a dead stop before entering the punching station of the machine. At this station the cards are aligned on all sides; top, bottom and sideways. This dual alignment positions the card to insure that the punches will be accurately correlated with the index point positions and therefore the card will be punched at the proper places.

The aligners for aligning the shorter or vertical sides of the card are spring-controlled and will centralize the card with respect to the punches.

The aligners for the horizontal edges consist of bottom stop aligners against which the card abuts and top aligners which are positively operated to force the card against the bottom stationary stops. After the alignment of the card the card enters the punching mechanism which consists of an oscillating type of punch and is controlled by interposers selected for operation by punch magnets. The punch and die assembly oscillates downwardly and upwardly and is moved downwardly at the same rate as the feeding of the card. A punch bail shifts the operated punch interposers to cause the punches to project through the card as the card is moving downwardly. Thus, it is unnecessary to stop the card for punching. The operated interposers are held in latched position as the punch is entering the card and the interposers and punches are positively brought back to home position under action of the punch bail.

The card is fed down to the eject station after punching and an eject mechanism is called into operation under control of a card operated lever to move the card out of the punching station. This eject mechanism moves the card in a horizontal direction out of the punching station and at a certain position of the card a card stacking mechanism is automatically called into operation to project the card forwardly towards the operator so that the stack of punched cards is stacked in a storage hopper in a location easily reached by the operator.

Storage unit.—The storage unit is of the electro-mechanical type and consists of a novel construction of a data setup and readout which enables the storage unit to be read out electrically to control the punches through the energization of the punch selecting magnets. Each column of the storage unit is split to represent in two readout portions 0, X, R and also 1—9. The setup in each column is controlled by electromagnets which are energized under control of the 1—9, 0 and alphabet character keys on the keyboard.

In order that the operator may know when each column has been set up and know the digit part of the setup, this information is afforded by sliding indicators which stop at digit positions to represent the digit setup 1—9 in the columns set up. The storage unit has a capacity equivalent to the eighty columns of the card so that a corresponding number of columns of both numerical and alphabetical information may be set up in the storage unit.

The operating mechanism of the storage unit is driven by a drive train from the main drive of the machine and will run continuously when the start switch is closed. Various mechanisms in the storage unit such as column reset devices, column spacing devices, etc., are initiated into operation by means of power operated cam units which are either actuated under control of keys, or by magnets energized by keys on the keyboard.

The columns of the card to be punched are numbered 1—80, from left to right, as is well known. The columns of the storage unit are correspondingly numbered and are set up in the order 1—80. If an error is located, all the columns of the storage unit which have been set up can be cleared of their representations. If there is a setting up to column 49, all forty-nine columns can be cleared out. Alternatively, if an error is discerned, the five columns which include the one in which an error has been made, can be cleared out without affecting the lower numbered columns set up. If there is an error in column 49, for example, columns 46—50 are cleared out and columns 1—45 remain set up. To this end there is provided sixteen clearing keys; one key for each group of five columns, and each operable to clear out the related group of five columns.

Means is also provided in the storage unit to automatically clear out all columns in the event that each card is to be punched to represent individually different data. In machines of this type it is desirable to punch a series of cards with common data, which is known as gang punching. To this end, means is provided in the storage unit to retain the setup for selected columns and the selective control for this purpose is under control of a punched control card which is punched in different rows at different index point positions to represent those corresponding columns in the storage unit in which a setup is to be retained. The control card is inserted in the storage unit and the associated suppression of reset control enables five different fields of the storage unit to be retained set up, even though other columns are reset.

While it is desirable that the setup should be retained for a series of cards when called for by a control card, nevertheless the possibility of resetting such fields of the storage unit selectively while the control card remains active is also desirable and to this end four keys are provided on the keyboard which, when operated, will nevertheless cause the resetting of related fields of the storage unit irrespective of the suppression of re-

set called for by the control card. The remaining field selected for suppression of reset by the control card can only be reset for a new setup by taking the control card out of the storage unit and then operating the resetting devices of the storage unit.

In the present machine three of the four fields in the storage unit are set up to represent a Major group classification, an Intermediate group classification and a Minor group classification. In card-controlled accounting it is desirable that upon a change in a Major group classification the two lower ordered groups, Intermediate and Minor, be also reset and further, a change in the Intermediate group requires resetting in the next lower order minor group. The Major, Intermediate and Minor reset keys on the auxiliary keyboard have an intercontrol which causes resetting of columns of the storage unit in one, two or three fields in the above combination corresponding to columns of the card perforated in the rows of the control card.

Master card unit.—In the master card unit the master card is placed on a card receiving bed with the 9 index point positions to be the first to be analyzed. At the beginning of the operation of the master card analyzing unit reciprocating grippers seize the shorter edges of the card to pass the card by the analyzing brushes so that the index point positions are read in a timed operation in the order 9-1, 0, X, and R corresponding with the correlation of the same index points of the card with the punches. Upon occurrence of perforations the punch selecting magnets are energized and, therefore, the card will be punched to represent the data on the master card. The analyzing brushes of the master card unit preferably terminate at plug connections so that selected columns of the card may be punched under control of the brushes analyzing the selected columns of the master card.

Keyboard.—The keyboard consists of keys which are depressible with ease by the operator to close electrical contacts to effect the desired function. The keyboard unit contains all of the digit and alphabet keys to set up the desired numerical and alphabetical information in the storage unit. Electrical interlocks prevent repeat operations if a key should be held depressed. The keyboard also includes a space bar which enables desired columns of the storage unit to be spaced over and omitted in the data setup operation. The suppression of reset keys—Major, Intermediate, Minor, Select skip and other functional keys such as Start, Stop, Reset and Dual card are mounted on the keyboard for easy accessibility.

The keyboard also includes a switch which starts the machine in operation, and other switches which control and select the manners of operation of the machine, such as a dual card type of punching, gang punching, automatic reset of all columns of the storage unit when a new setup is to be effected for each card, a master card switch which renders the master card unit effective for operation, and an auto start switch which automatically initiates the operation of the card punching machine when the last column of the storage unit has been set up.

The structural details of the card punching machine follow and as far as it is possible the functions of the machine will be described in the sequence that the operations of the machine take place.

Card feed from supply magazine and card feed to visible reading station

The power for operating the punch unit is derived from any suitable electrical motor, the armature shaft of which has a belt connection 10 (Figs. 2 and 3) to a pulley 11 secured to a drive shaft 12. To shaft 12 there is secured a pinion 13 (Figs. 3 and 4) meshing with a gear 14 loose upon a drive shaft 15. Secured to gear 14 is a clutch disk 16 and in view of the continuous operation of the motor, clutch disk 16 constantly rotates in a clockwise direction (Fig. 3).

Arm 17 is secured to the drive shaft 15 and carries a clutch pawl 18 which is urged by a spring 19 to engage a tooth of the clutch disk 16 but is normally prevented from doing so by a pivoted clutch arm 20. When clutch arm 20 is attracted by the energized UCM card feed clutch magnet 21, arm 20 will be shifted to unlatch clutch pawl 18 which thereupon engages a notch of the clutch disk 16 to drive shaft 15 for a complete revolution. At the end of the one revolution drive of shaft 15, clutch pawl 18 is again engaged by the clutch arm 20 which, in the meantime, has come to normal position due to the deenergization of magnet 21 and the clutch connection is broken. The above is a general description of a well known form of electromagnetically controlled clutch employed in machines of the type now being described. The clutch just described is called herein the UCM or "upper clutch."

The drive shaft 15 carries at the end opposite the clutch a disk 22 (Figs. 2 and 5) which carries a screw stud 23 and between the stud 23 and a screw stud 24 carried by a rock arm 25 is a connecting link 26. Since stud 23 is offset from the center of shaft 15 it will cause, as the shaft 15 is driven a complete revolution, the rocking of the arm 25 and a shaft 27 to which said arm 25 is connected.

The card supply magazine 28 at the rear of the machine (see Fig. 1) is shown in section in Figs. 6 and 7 and in this magazine a supply of blank or written-on cards 29 to be punched is placed, either to represent like data for gang punching, or individual data for detail cards. At the bottom of the magazine there is slidably mounted a rack slide 30 carrying a card picker 31 (Fig. 7). Meshing with the rack teeth of the rack slide 30 is a segment 32 carried by the rock shaft 24. Through the drive and interlinkage just described the picker 31 is reciprocated so as to feed the lowermost card out of the supply magazine 28 and through a conventional throat which restricts the feeding of a card to a single one. As the cards emerge from the magazine 28, fed in the manner just described, they are moved vertically downward to a visible reading station 30 (Fig. 1). This station is so characterized because it places each card fed from the magazine into a position where any written data thereon is visible to the operator through a glass 33 (Figs. 1, 6 and 7). It is explained that the cards are placed in the magazine with the printed or written face downward and fed with the 9 index points leading. It is evident that feeding of the well known type of card used to control accounting machines to the visible reading station 30 will position it upright for interpretation or transcription by the operator in the visible station.

The purpose of bringing each card into view is to enable the operator to determine if any written data thereon is to be transformed into card punchings, this being performed under con-

troil of a keyboard and associated setup storage device which subsequently controls the punching portion of the machine.

Reverting now to the card feeding mechanism for the supply magazine, it will be noted that emerging cards are first fed by a pair of feeding rollers 34, 35 (Figs. 2 and 7), to feeding rollers 36 and thence to the next lower pair of feeding rollers 37, 38 which are at the bottom of the visible card reading station. The rollers 35 are spring-pressed against the contact rollers 34 and rollers 38 similarly with respect to rollers 37. The feeding rollers 36, however, merely press the card against the glass plate 33. Rollers 34, 36 and 37 are rotated by a gear drive described as follows:

The drive shaft 15 has secured to it a gear 39 (Fig. 3) (similar to the gear 14) which meshes with a gear 40 on a stud shaft 41. The latter has secured to it a gear 42 (see also Fig. 2) meshing with a pinion 43 secured to the drive shaft 44 of the rollers 36.

Attached to the gear 43 is a gear 45 (Figs. 2 and 3) in mesh with a gear 46 secured to the drive shaft 47 of the rollers 34. Gear 45 also meshes with a gear 48 secured to the drive shaft 49 of rollers 37. Summarizing, the engagement of the one-revolution clutch controlled by clutch control magnet 21 will operate the card picker and the associated card feed rolls so that in each cyclic operation of the drive shaft 15 the card will be fed from the supply magazine to the visible reading station 50 (Fig. 1).

Card feed drive and card feed to punching station

The cards to be punched are fed from the visible reading station to a card punching station. The card feed drive for the punching station operates concomitantly with the card feed drive for the visible card reading station so that upon the presence of a card in the latter station the next cyclic operation of the machine will feed it to the punching station. Thus, two successive cyclic operations of the machine are required to feed the card from the magazine to the punching station.

The card feed drive through the punch mechanism and, in fact, the operation of the punching mechanism is initiated by the energization of an LCM punch control magnet 61 (see Fig. 4) which controls a clutch known herein as the "lower clutch." The energized magnet 61 attracts its armature 62 which is also a clutch release arm to release a clutch pawl 63, carried by an arm 67 secured to a drive gear 91. The freed clutch pawl 63 is rocked by its spring 64 to engage the tooth of a ratchet wheel 65. The aforementioned constantly rotating pinion 13 is also in mesh with a gear 66 secured to a shaft 68 and fastened to shaft 68 is the constantly rotating ratchet wheel 65. This description pertains to a well known form of clutch which enables one complete revolution of drive gear 91 for each energization of clutch magnet 61. From gear 91 various gear drives are effected, one of which is for driving the sets of card feed rollers related to the punching station.

Referring to Figs. 7 and 8, it will be noted that the card emerging from the supply magazine 28 passes between the glass plate 33 and a rearward guide plate 69 to thus guide the card to the visible reading station. Cards emerging from the visible reading station are guided to the punch station by the aforementioned rear guide plate 69 and a forward guide plate 70.

A card at the visible reading station is held in

fixed position by rollers 34-35 and 37-38 and the rotation of the latter rollers will feed the card to aligning position, rollers 71 and 72 being the entering feed rollers to the punching station. 5 Feeding rollers 72 are spring-urged (see Fig. 8) into contact with the rollers 71, which latter are mounted on a drive shaft 73. Gear drive connections are provided from the drive gear 91 to the feed roller shaft 73 which are best shown 10 in Fig. 4. Secured to the drive gear 91 is a mutilated gear 74 driving a mutilated gear 75 secured to the feed roller shaft 73. At the beginning of the clockwise rotation of the drive gear 91 the teeth of gear 74 will mesh with the teeth of the gear 75, after which gear 75 will come to rest 15 and stay at rest during the time the gear 91 completes its movement. During this rest period of the feed rollers 71 a separation is effected between it and the associated feed rollers 72 to bring it out of contact with the surface of the card being fed so that during this period an aligning mechanism may function to align the card, both at vertical and horizontal edges.

The punching station is also provided with discharge feed rollers 76 and 77, shown in Fig. 8 and drive connections are provided from shaft 68 to constantly drive feed roller shaft 78 for the feed rollers 76. Referring to Fig. 4 secured to the constantly rotating ratchet wheel 65 is a gear 79 (shown dotted) meshing with a gear 80 secured to the feed roller drive shaft 78. Thus, the feed rollers 76 are continuously rotated.

From the aforementioned gear 91 there are gear drive connections to operating shafts of the 35 punching mechanism for operating mechanisms in related timing. Referring to Fig. 4 secured to gear 91 is a gear 92 loose on a stud shaft 94. Secured to drive gear 92 is a larger gear 93 (Fig. 4) meshing with a pinion 95 secured to a punch cam drive shaft 96. This gearing provides sixteen revolutions of drive shaft 96 for each punch cycle, because the punch cycle is on a sixteen point basis, twelve revolutions being utilized for R, X, 0, 1-9 index point punching, as will be 40 explained.

Attached to shaft 96 is a gear 102 (Fig. 7) which drives a gear 105 secured to a drive shaft 104 through an idler gear 103. Shafts 96 and 104 are the main drive shafts of the punching 50 mechanism.

Gear 91 meshes with a gear 97 (Figs. 2 and 4) secured to a shaft 98 and secured to shaft 98 is a gear 100 in mesh with a gear 101 secured to a drive shaft 99 which drives the cams for operating the LCI-14 electrical contacts. These cam contacts close and open only during the 55 punching cycle.

Referring to Figs. 5 and 6 shaft 78 carries cams for operating the CR1-5 cam contacts and thus 60 these contacts close and open continually.

Alignment of card at punching station

Before entering the punching mechanism proper, the card is aligned both at the vertical and horizontal edges so that the card will enter the punching mechanism with the proper registration between the punches and die. The alignment of the card at its leading horizontal edge is provided by causing this edge of the card to strike fixed stops. It will be recalled that the card as it is fed vertically is guided by plates 69 and 70. Referring to Figs. 8, 10 and 11 adjacent the guide plates 69 and 70 are card stops 110 which consist of slotted plates guided by the 65 heads of screws 111 carried by a support bar 112.

A rock shaft 113 carries short rods 114 which fit in holes in the related card stops 110. For rocking the shaft 113 to thereby project the card stops 110 into the path of a card being fed, the operating mechanism shown in Figs. 8, 10 and 11 is provided. Secured to the cam drive shaft 15 is a profile cam 115 with which cooperates a spring-urged follower 116 secured to a rock shaft 117. To the shaft 117 there is secured an arm 118 having an open slot and pin connection to an arm 119 secured to the rock shaft 113. Cam 115 is so timed as to rock shaft 113 counterclockwise to project card stops 110 just prior to the time that the leading horizontal edge of the card reaches the bottom of the card guide plates 69 and 70.

It will be recalled that the feed roller 72 (Fig. 8) is spring-urged into cooperation with the related feeding roller 71 and it is therefore desirable to separate or open such feed rollers just before the aforementioned card stops come into operation. To this end, as shown in Fig. 6 there is loosely pivoted on studs 120 carried by side frames a pair of bell crank follower arms 121, each of which cooperates with a profile cam 122 driven by cam drive shaft 15 (see Fig. 10). The vertical arm of each bell crank 121 has a lateral portion which abuts the drive shaft of the feed roller 72. Cams 122 are timed to operate bell cranks 121 to open the feed rollers to enable the card to be freely projected downward against the card stops 110. This projecting movement downwardly is effected by the means shown in Figs. 8, 10, and 12. Loosely mounted on the rock shaft 117 are bail fingers 126 which project in slots 127 in the guide plates 69 and 70. Integral with each bail finger 126 is a follower arm 128 cooperating with a related profile cam 129 secured to drive shaft 15. At about the time the following edge of the card clears feeding rollers 37 and 38 (Fig. 8) and strikes the card stops 110, cams 129 rock the bail fingers 126 to strike the upper horizontal edge of the card and forcibly project it against the lower card stops 110. The card is thereby aligned at both the lower horizontal edge and the upper horizontal edge.

Means is further provided to align the card along its shorter vertical edges and these side aligners are spring-controlled and will centralize the card in respect to the punches sideways. The preferred arrangement is best shown in Figs. 8 and 10.

The shifting of the card by movement at the vertical edges is effected by aligning fingers 130 and 131, each of which is pivoted at 132 to a bracket 133 carried by the guide plate 70. The finger 131 has connected thereto a link 134 and the finger 130 to link 135 and between such fingers a tensioned spring 136 is interposed. Under the influence of spring 136 finger 131 is moved to the left as viewed in Fig. 10 and a finger 130 to the right but such action is prevented until a predetermined time in the cycle by cam 142 (Fig. 8) driven by shaft 15 and is effected by the following described means:

Pivoted by a pin 141 carried by a bracket 137 which is carried by guide plate 70 is a triple armed member having arms 138, 139, 140 (Fig. 10). Arm 139 is pivoted to link 135, arm 138 cooperates with a follower bell crank arm 143 loosely pivoted on rock shaft 117, and arm 140 carries an adjustable screw 142. Also pivoted on pin 141 is a two-armed member, one arm 144 being pivoted to link 134 and the other arm 145 cooperating with screw 142. Normally, the system is held in the position shown

in Fig. 10 by coaction of arm 138 with follower bell crank arm 143, and the latter with cam 142. At the time the card to be aligned is free of the feeding rollers 72—73, and has engaged the card stops 110, arm 143 is spring-operated under influence of cam 142 to allow arm 138 to move as a result of the initial tension in spring 136. The system thus moves counterclockwise about pivot pin 141 and aligning fingers 130, 131 moves towards each other, shifting the disaligned card, if it is out of alignment, to the proper position. The limit position of fingers 130, 131 determine this position. After the card is properly aligned, both vertically and horizontally, rollers 72, 73 close upon each other, and card stops 110 are moved out of the path of the card, so that the aligned card is now fed to the punching mechanism.

As the card enters the aligning position the lower card edge engages a cam edge 146 (Fig. 12) of a double arm 147 pivoted at 148. The arm 147 (Fig. 13) is rocked by the card to close card lever contacts 149, the purpose of which appears in the wiring diagram especially in connection with gang punching.

Punching mechanism

The punching mechanism will be described particularly in connection with Figs. 6, 7, 8 and 9. In general, the card is punched at selected index point positions by an oscillating type of punch, that is, the punch and die assembly repeatedly oscillates, down and up, and in the downward movements in synchronism with the feeding of the card index point by index point. Thus, the card being punched while in motion, it is unnecessary to stop the card while being punched.

The side frames 150 and 151 of the machine support a rock shaft 152 (Figs. 6, 8, and 9) and secured to shaft 152 is a depending casting 153 (Fig. 8) to which is secured by screws 154 a transverse reciprocable punch bail plate 155 (Fig. 8). Referring to Figs. 6 and 9 secured at each end of shaft 152 is a three-armed follower member 156 which cooperates with complementary cams 157 carried by the punch drive shaft 96. The complementary cams 157 are so arranged that for each revolution of shaft 96 the complementary cams will rock shaft 152 to reciprocate the bail plate 155, first to the right and then to the left and one reciprocation for each index point to be punched.

Pivoted mounted on a fixed rod 158 (Figs. 7 and 8) carried by the side frames 150 and 151 (Fig. 9) is a pair of side frame plates 159 and 160, each of which carries follower rollers 161 cooperating with complementary cams 163 secured to the punch drive shaft 96. The side plates 159 and 160 carry a box-like structure 162 (Figs. 8 and 9) which includes forward and rearward guide plates which have rectangular holes in which are slidably mounted the eighty rectangular shaped punch pins 164. Also, carried by the box-like structure 162 in any suitable manner is a die structure 165 having die holes in which the punch pins 164 project during the punching stroke. A separation in alignment with guide plates 69, 70 is provided between the punch pin supporting box 162 and the die structure 165 through which the card to be punched passes without interference, the slot thus formed being greater in a horizontal direction than the horizontal dimension of the card to be punched. Cams 163 are so designed as to move the punch pins and die by their supporting structures down-

wardly at the same rate the card is being fed, and restored at such rate that the punch pins will be correlated with the next index point to be punched. While the punch pins and die move downwardly the punch bail plate 155 is reciprocated to effect punching.

Each of the punch pins 164 is pivoted by a pin 166 to a punch interposer 167. In the normal unlatched position of an interposer 167 the forward edge rests upon a shoulder 168 of a latch member 169 which is pivoted on a rod 170 carried by a support bar 171. When an interposer 167 is actuated, i. e. rocked counterclockwise about pin 166 by means to be described, the forward edge will be removed from shoulder 168 to rest upon a shoulder 168a, latch member 169 being rocked by spring 169a interconnected between an interposer 167 and related latching member 169 to hold the interposer 167 in latched position.

When an actuated interposer 167 is latched by member 169 a notch 172 therein will receive the lower extremity of the punch plate 155 and thus an operative connection is made between the punch pin 164 and the punch bail plate 155. This selective connection is effected under control of the punch selecting magnets 173, each of which when energized attracts its armature 174 to depress a plate 175 downwardly. Each plate 175 has an open slot and pin connection to a double arm 176 which has a pivot connection 177 to a link 178 which has a pivot connection 179 to the related interposer 167. An impulse is transmitted to the magnet 173 at the beginning of a cycle point to attract its armature 174 downwardly, moving plate 175 in the same direction and double arm 176 counterclockwise, elevating the link 178 to rock the interposer 167 about the pivot connection 166 with the punch pin 164. The notch 172 of the latched interposer will now be received by the punch plate 155 and then movement of the latter to the right as viewed in Fig. 3 will cause the punch pin 164 to pass through the selected index point of the card and into the die 168. As the punch pins 164 are projected through the card the latched interposer 167 will be held in latched position by latching member 169 until the extreme right hand position of interposer 167 is reached. All of the above operations are timed so as to punch the card at the selected index point while it is being fed downwardly synchronously with the downward movement of the punch pins. Of course, if an interposer 167 is not rocked or latched the interposer will not have its notch 172 received by the bail plate 155 and the related punch pin 164 will not be projected to punch the card.

After punching each of the selected index points the motion of the punch plate 155 to the left as viewed in Fig. 8 positively retracts the punch pins 164 and interposers 167 to their normal position through surface 172a. For the purpose of unlatching the latched interposers 167 to be in readiness for punching the next index point the operating shaft 104 which revolves once for each cycle point is provided with an arcuate cam projection 180. Just before the latched interposer 167 reaches the extreme right hand position a tail 169b of latching member 169 strikes the index surface of bar 171. At the extreme right hand position of interposer 167 the latter moves off the step 168a of the latching member 169 because lever 169 cannot follow interposer 167 and spring 169a now rocks the interposer to cause it to latch on step 168. The cam projection 180 engages the tail portions 181 of all latched interposers to rock

them if they have not been rocked in the manner just described. While the interposers 167 are now unlatched, nevertheless the bail plate 155 strikes the edge 172a to restore the interposers to home position.

The present machine has provision for punching eighty columns of the card and therefore the punch plate 155 in the machine is of considerable width co-extensive with the horizontal dimension of the card to be punched. It is further obvious that the movement of the punch plate 155 is effected by moving each end under control of the complementary cams 157. It is desirable to provide for movement of the punch plate 155 intermediate such end positions so as to prevent bowing of the punch plate 155. To this end, there is supported by the shafts 96 and 152 a plurality of frames, each of which consists of a pair of side plates 185 (Fig. 9) and a cross plate 186 (Fig. 8). Such plates carry a block 184 in which is slidably mounted a plunger 187 actuated by a related cam 188 secured to the drive shaft 86. The cams 188, through plungers 187, move the punch plate 155 at one or more points intermediate the ends in timed relationship with the rocking of the punch plate 155 by the complementary cams 157. Thus, an additional intermediate thrust is exerted upon the punch plate 155 to insure that all of the punch pins 164 irrespective of their position will be actuated to punch the card.

After the card has been punched the card is fed further downward to an eject station where it is fed horizontally or in a direction transverse to its downward feed. The ejected cards are stacked in a hopper and the operating mechanism for effecting the ejection of the punch card and stacking will now be described.

Card ejecting mechanism

As the card is being punched it is guided to the lower part of the machine by spaced guide plates 195 and 196 (Fig. 7) which are suitably apertured so that feed rollers 85, 87 project therethrough to contact the surfaces of the card and thereby feed the punched card.

The feed rollers 85 are continually rotating feed rollers and are driven from the constantly rotating shaft 78 by the following described means:

To shaft 78 there is secured a gear 81 (shown best in Fig. 6) which meshes with a gear 82 (Figs. 2 and 6) which is secured to the feed roller shaft 82 of feed rollers 71. Secured to feed roller shaft 82 is a gear 84 (Figs. 2 and 6) which drives a gear 85a secured to the feed roller shaft 89 of feed rollers 85 through a gear 88 secured to a shaft 105. Through this gear driving train feed rollers 76, 77 and 85 constantly rotate. Rollers 87 are spring-pressed against rollers 85 and through frictional contact also constantly rotate.

Referring to Figs. 2, 7 and 14 secured to shaft 105 is a bevel gear 106 meshing with a bevel gear 107 secured to a spindle 108 to which is secured an eject roll 109. The surface of the latter is formed of a resilient gripping material like sponge rubber and passes through an aperture in plate 195 (Fig. 14) to cooperate with a normally separated feed roll 200.

Referring to Fig. 16 when the leading edge of the card reaches the lowermost position it will rock a card lever 197 to close card lever contacts 198. As will appear later in connection with the description of the wiring diagram, closure of contacts 198 will cause the energization of an

eject solenoid 189 (Figs. 6, 7, 15 and 17) and by means now to be described this will result in the separation of the feeding rollers 85 and 87 but cause the eject roller 109 and a cooperating feed roller 200 to come into contact with each other to thereby feed the card transversely with respect to its downward direction of feed.

Referring to Fig. 15 the core 205 of the solenoid 189 has a pin pivot connection to a bell crank comprising arms 206 and 207, and the arm 207 when rocked clockwise in Fig. 15 or rearwardly as in Figs. 14 and 17 will position the roller 200 to have a peripheral frictional contact with the eject roller 109. To the guide plate 196 there is secured a bracket 208 carrying a pin 209 on which a U-shaped frame 210 is pivoted. The U-shaped frame 210 carries the spindle 211 of the cooperating eject roller 200. The cross plate 212 of the U-shaped frame has a left hand projection 212 (Figs. 14 and 17) which is engaged by the arm 207 so that when said arm is rocked as a result of the energization of solenoid 189 it will rock the U-shaped frame 210 about the pivot 208 to position rollers 200 into contact with eject roller 109. At the same time feed rollers 87 are separated from rollers 85 to free them from contact with the card to enable eject rollers 109, 200 to feed the card transversely, to the left as viewed in Figs. 14 and 17.

Referring to Figs. 6, 14 and 17 the guide plate 196 carries a ball shaped frame 213 which supports a pivot pin 214 on which is mounted a U-shaped frame 215. The upper extensions of the U-shaped frame 215 carry the spindle 216 on which rollers 87 are rotatable. A spring 217 (Fig. 14) extended between the guide plate 196 and the cross plate of the U-shaped frame 215 normally causes the peripheral contact of the rollers 85 and 87.

Referring to Figs. 14 and 17 the cross plate of the frame 210 has a right hand extension 218 which is in contact with a leaf spring 219 attached to the U-shaped frame 215 by a bolt 220. Thus, the rocking of the frame 210 in a manner previously described will cause extension 218 to contact with the leaf spring 219 to rock the frame 215 to bring eject rollers 87 out of contact with rollers 85. Eject rollers 109, 200 now feed the card laterally or to the left as viewed in Fig. 17 and to a position where the punched card is shifted into a stacker or storage hopper.

Referring to Fig. 1 it will be noted that the downward travel of the card to be punched is from the supply magazine 28 to the visible reading station 50, thence through the punching mechanism which has been described to the lowermost position. The punched card is then fed laterally to the left as viewed in Fig. 1 by the ejecting mechanism just described and then by a stacking device shown in Fig. 18 now to be described, the stacked cards are shifted in stacked relationship in a magazine 221 where they are accessible to the operator.

Referring to Figs. 2 and 4 gear 80 drives a gear 235 secured to eject roller shaft 222 through an idler gear 236. Shaft 222 thus constantly rotates and has a bevel gear connection 223 (Fig. 18) to a spindle 224 of a rubber eject roller 225. The latter cooperates with a smaller eject roller 226. Eject rollers 225, 226 continually rotate.

The eject rollers 109, 200 eject the card to the left as viewed in Figs. 1, 14, and 18 so as to pass between guide plates 227 and the leading edge of the card is then seized by the rollers 225, 226 to pass in front of a pair of solenoid operated

card stacking plates 228 and 229, which are normally in the full line position in Fig. 18. The stacker plates 228, 229 are pivoted upon respective shafts 230, 231 and said shafts carry intermeshing segments 232, 233. An interconnected spring 237 maintains stacker plates 228, 229 in the full line position. Rock shaft 230 has a link connection 238 to the core 233 of a solenoid 234. At a timed operation the solenoid 234 is energized to attract its core 233 inwardly which will, through the connections just described, rock shaft 230 counterclockwise and shaft 231 clockwise at the time that the ejected card is in front of the stacker plates 228, 229. Movement of the stacker plates to the dotted position shown in Fig. 18 will push and shift each card forward so that each is out of the path of the next incoming card, and thus the punched cards 28 are stacked upright in magazine 221 and in front of the operator.

20 Split construction of card feeding mechanism

While the feeding mechanism just described will efficiently feed the cards from the supply magazine to the place of ejection, nevertheless, due to a poor condition of a card to be punched it may jam in the card feed. To facilitate the removal of such cards and further for the purposes of inspection it is desirable to construct the card feeding mechanism so that the cooperating feeding rollers may be separated. To this end, the series of feeding rollers 35, 36, 38, 72, 77, 85, eject roller 109 and other parts shown in Fig. 7 to the right of the path of the card are carried by a unitary frame 240 which is pivoted on a rod 241. The frame 240 may be rocked to the dotted line position shown in Fig. 5 and held in such position by a forked arm 242. Thus, all of the aforementioned feeding rollers are now separated for the purposes just explained.

To a shaft 243 (Fig. 7) there is carried a finger piece 244 and said shaft 243 carries arms 245 having rollers 246 cooperating with fixed cam surfaces 247 (Fig. 5). In the position shown in Figs. 5 and 7 the frame 240 has been cammed to normal position. Rocking of the finger piece 244 upwardly as viewed in Fig. 7 will remove rollers 246 from fixed cam surfaces 247 now unlocking frame 240. When the frame is returned to normal the reverse operation will cause, by the coaction of rollers 246 and cam surfaces 247, the positioning of the frame 240 inwardly to the proper position.

Master card analyzing unit

55 By means of this unit the data on the master card is analyzed to effect the selective energization of the punch selecting magnets 173 to transfer the data on the master card to detail cards. The master card is analyzed by analyzing the horizontal rows of index points thereof in succession in the order 9-1, 0, X, R and in timed relation with the passage of the corresponding index point positions of the detail card past the punches 164. Hence, the selective operation of these punches will duplicate the data on the detail card.

There are gear driving connections from the continually rotating main drive shaft 68 to the operating shaft 250 (Fig. 3) of the master card analyzing unit and as will appear later in the description of the wiring diagram the operating shaft 250 is selectively clutched by the energization of an MCM clutch control magnet 251.

From Fig. 3 it will be seen that secured to shaft 68 is a gear 252 and from said gear 252

there is a gear driving train 253, 254, 255, 256 and 257 to a ratchet clutch disk 258 loose on shaft 250. 259 represents a one-revolution clutch of a type similar to that previously described which, upon energization of clutch control magnet 251, causes a clutch connection between ratchet wheel 258 and the drive shaft 250. One revolution of drive shaft 250 causes the operation of the master card unit which is shown in detail in Figs. 19-23, inclusive.

The master card unit is located at the left of the machine as viewed in Fig. 1 and is just to the front of the card hopper 221 but disposed below so that stacking of the punched cards in the hopper will not interfere with the positioning of a master card in the analyzing unit.

Referring to Figs. 19 and 20 the master card is positioned in an open portion at the left front of the machine so that it fits between side plates 260 of cover plates 261 and beneath spring clamps 262 which are carried by a vertical portion of a plate 263 which is the bottom of the card hopper 221. The master card is placed upon a stationary table 264 of insulating material so that the trailing edge cooperates with a pair of card picker blocks 265 which project upwardly from the plane of the table 264. The master card is inserted in this position prior to a cyclic operation of the machine and if the same data is to be commonly duplicated for a series of cards, which is called "gang punching," the master card is retained in the master card analyzing unit. When the data to be duplicated is to be changed, another master card is substituted for the old one; thus, a simple change of control of the data to be duplicated is afforded and easily accessible to the operator.

The master card is analyzed by gripping and moving the card over the stationary table 264 inwardly past analyzing brushes 266 (Figs. 20 and 23) in timed relation with the feeding of the detail card past the punches. Referring to Figs. 20, 22 and 23 at each side of the master card unit and extending from the front to the rear are fixed guide shafts 267 and 268, each of which slidably supports a rack member 269 and 270, provided with rack teeth 271 underneath meshing with a related gear 272 and the oscillation of the gear 272 moves each rack member 269 and 270 from the front to the rear and backward. Projecting from each rack member 269, 270 is a pin 273 (Figs. 19 and 22) which works in a related slot 274 formed in each cover plate 261. The rack members 269 and 270 carry blocks 275 (Fig. 23) of insulating material and are spaced the width of the card. The rack members 269 and 270 also carry rods 276 which provide the pivots of card grippers 277 and as is shown dotted in Fig. 22, four of these grippers 277 are provided at each side and they are normally raised above the upper surface of the related block 275 to enable the insertion of the master card so that the left and right marginal edges are below the grippers 277 but on top of the stationary table 264 and carriage blocks 275.

In the normal position of the card carriage blocks 275 shafts 267 and 268 are rocked slightly so that scalloped cam portions 278 thereof engage with the tails of the grippers 277 to rock said grippers against the action of spring-pressed plungers 279. After the initial movement of the carriage inwardly of the machine, shafts 267 and 268 come to the position shown in Fig. 23 and the four grippers 277 on each side are now under the action of plungers 279 to firmly grip the card against the blocks 275.

It should be noted that the card pickers 265 are not carried by the carriage blocks 275 but are so mounted that they follow the initial movement of the carriage blocks 275 to feed the master card until it is gripped at each side by grippers 277. Referring to Fig. 20, a plate 280 is formed as a bail to carry a rod 281 on which is slidably mounted a U-shaped bail plate 282 to which the related card picker 265 is secured by fastening screws 283. Screws 283 pass through slots 284 (Fig. 19) in the card picker 265 as a means of adjustment. Encircling the rod 281, as shown in Fig. 20, is a compression spring 285 which projects against the bail 282 at one end and against a collar 286 fixed to the rod 281. In the normal retracted position of blocks 275, each forward end abuts a portion 265a of the related picker 265 (see Fig. 19) to normally compress each spring 285. As the blocks 275 move rearwardly, each picker 265 follows to push the master card over the table, and before the pickers move their limit which is regulated by the collar 286 the grippers 277 have seized the card so that blocks 275 thereafter move the master card past the analyzing brushes 266.

The analyzing brushes 266, of which there are eighty, one for each column of the card, are carried by a block 290 of insulating material. A pair of arms 291 (Figs. 20 and 22), each pivoted at 292, carry the block 290 by means of assembly pins 293. Articulated at 294 to each arm 291 is a related follower arm 295 having a roller cooperating with the respective cam 296 secured to the drive shaft 250. During the inward movement of the card carriage effected by means to be described, the rollers of follower arms 295 will cooperate with the high portion 296a of cams 296, maintaining the brush carrying block 290 in the position shown in Fig. 20 so that said brushes 266 will pass through the card perforations to contact a metal contact roller 287, fixedly carried by the side plates 260. This analysis is so timed as to occur during the time that the corresponding index point positions of the detail card pass the punch pins and brushes 266 close circuits to the punch selecting magnets 173 to select the desired punches. During the return or forward movement of the card carriage the rollers of follower arms 295 cooperate with lower portions 296b of cams 296, thereby causing the depression of the brush carrying block 290 to prevent contact of brushes 266 with the card perforations while the card is being returned. The reciprocation of the carriage is effected by the arrangement shown in Fig. 22, wherein it will be seen that secured to each end of shaft 250 are complementary cams 297 which cooperate with a follower arm 298 which is provided with a segmental rack portion 299 cooperating with a pinion 300 secured to the shaft 301 to which the pair of gears 272 are secured. Complementary cams 297 are of such formation that they will reciprocate the segment 299 to rotate the pinion 300 first clockwise as the rack 299 descends and then counterclockwise as it returns. This counterclockwise and clockwise movement of shaft 301 will correspondingly oscillate gears 272 so as to move rack members 269 and 270 and the master card carriage to and fro.

Reference has been made to the grippers and the fact that they are normally open but close upon the card after the initial movement of the carriage. To effect this, shafts 267 and 268 carry pinions 302 (see Fig. 2) which mesh with a slidably mounted rack 303. Said rack 303 has a bent-over portion 304 carrying a roller 305 (Fig. 19) cooperating with a cam 306 secured to the shaft

250. At the initial operation of the machine the roller 305 cooperates with the cam portion 306a and in such position shafts 267 and 268 are turned so as to cam grippers 277 away from the blocks 275. After the initial movement of the card carriage rearwardly, roller 305 moves out of such cam portion 306a to enter the portion 306b, thus rocking the shafts 267 and 268 to the position shown in Fig. 23. Grippers 277 are now free to be activated by spring-pressed plungers 279 so as to firmly grip the cards.

During the reciprocating movement of the brush carrying block 290 ferrules 307 (Fig. 20) which carry the brushes 266 constantly bear against contact springs 308 carried by related ferrules 309. From the ferrules 309 there are wire connections to plug sockets which, in turn, can be plugged as shown in the wiring diagram to plug sockets leading to the punch selecting magnets 173.

Setup storage unit

The storage unit comprises an electromechanically operated data setup unit in which alphabet or numeral data is set up under control of numeral and alphabet keys of a keyboard. The data set up has a capacity of eighty columns corresponding to the card and punching capacity and the data is set up column by column automatically as the alphabet or numeral keys are depressed. When the eightieth column of the storage unit has been set up, either by a start key or automatically, a cyclic operation of the punching machine is initiated which causes the reading out of the data set up in the storage unit timed with respect to the passage of the index points of the detail card by the punches to select punches in accordance with the data set up in the storage unit. As will be later evident the numerical part of the setup in the storage unit is made visible by indicators which enable the operator to verify the data set up and to correct errors prior to punching the card.

The construction of the storage unit is represented in Figs. 26 to 32, inclusive. The storage unit SU is mounted at the right hand lower portion of the machine as shown in Fig. 1. The cabinet portion of the machine at the right side is recessed to enable the unit to be swung about as a pivot and placed within the confines of the cabinet proper to conserve floor space. In Fig. 1 it is shown in the position it would assume when the unit is out for operation because in this position the verifying indicators are visible and error correction keys are accessible. The framework of the storage unit includes for the electrical setup portion of the unit side frame members 321 and 322 (Fig. 24) which are of insulating material to prevent grounding of the electrical parts. A cross member 320 is utilized to provide a rigid framework and others which will be referred to as the description progresses.

The numeral or alphabet data setup is controlled by a series of twelve magnets 323 (Figs. 26 and 27), nine of these being provided to effect the setup of digits 1-9 and three for setting up 0, X, and R representations, so that a combinational setup is made in two portions. The 0, X, R setup is used in combination with a 1-9 setup when alphabetic data is to be set up in a column. Each of these magnets and related operating mechanism is alike in construction so that a description of one will suffice for all. The digit setup 1-9 will now be given in detail and refer-

ring to Fig. 29 the armature 324 of each magnet 323 is pivoted on a pin 325 and connected to each armature 324 is a slotted link 326 slidably mounted on a pin 327. The link 326 is not contiguous but is broken by an insulating connection 328 which has a projection 329 to operate a contact blade 330 to thereby close the connection between terminals 331 and 332. Pivoted on a stud 333 is a double arm 334, one end of which abuts a pin 326a secured to the end of link 326 and the other against an adjusting screw 339b. The closure of a contact by a key of the keyboard will cause the related magnet 323 to be energized and thereby attract its armature 324 and at the same time connecting terminals 331 and 332. These terminals in fact are contacts in the holding circuit for the magnet 323 to insure that the magnet is retained energized for a short time after the key has been released. As a result of the attraction of armature 324, the link 326 will be shifted to the right as viewed in Fig. 29, rocking the double arm 334 counterclockwise.

Through the rocking of each arm 334 the digit setup is made on the setup device now to be described.

Fixedly mounted in the insulating side plates 321 and 322, so as to be immovable, are nine digit bars 335. Each of these bars has the digit value indicated in Fig. 26. Each digit bar 335 has a series of slots 336, one for each column, and for the same column the slots 336 for all bars 335 are in alignment. Each digit bar 335 carries a plurality of studs 337, only one of which is shown in Figs. 29 and 30, each of which extends through a related slot 338 in an adjacent bar 339 which carries a related screw 339b. Hence, by such means bar 339 is slidably mounted on the paired immovable bar 335. From Fig. 26 it will be seen that bars 335 and 339 are paired and bar 339 covers the adjacent bar 335 and in the normal position of each paired bar 335 and 339 the slots 340 (see Fig. 26) formed in the movable bar 339 are aligned with the slots 336 in the fixed bar 335. Hence, it will be obvious that in the normal position of all the fixed digit bars 335 and associated movable bars 339 the slots are in columnar alignment in all eighty columns. Means is provided under control of each magnet 323 to bring the teeth 341 (Fig. 30) intermediate the slots 340 of the movable bar 339 over the slots 336 of the paired fixed bar 335 so that a stop may be provided in each column by each movable digit bar 339. To prevent grounding to the machine frame of the electrical digit bar 335 by the bar 339 since each pair of these bars is in direct electrical contact, the bar 339 has an upward extension 342 which is insulatably mounted therefrom by a juncture plate 343 of insulating material. Each fixed digit bar 335 has attached thereto a terminal 344 to which a wire connection is made as will appear later in the wiring diagram. Interconnected between each pair of bars 335 and 339 is a normally tensioned spring 356 (Figs. 29 and 30). The actuation of the double arm 334 will, through the adjusting screw 339b, shift the movable bar 339 to the left to tension spring 356 and by the teeth 341 cover the slots 336 in all columns of the paired fixed digit bar 335. This closure enables the differential setting of a segment 345 (Fig. 26) of a released column. It will be noted that the pairs of bars 335 and 336 are radially mounted with respect to the center of a shaft 346 on which the eighty segments 345 are pivoted. Extending radially 75 from the center of shaft 346 is a metal plate 347

21

which is connected to the related segment 345 by a juncture plate 348 of insulation. Plate 347 carries a pivot pin 349 on which is pivoted a contact pawl 350. A spring 351 is extended from a depending portion 352 of contact pawl 350 and a spring clip portion 353 of plate 347, causing the pawl 350 to be normally in the position shown in Fig. 26.

Assuming now that the segment 345 related to the first column to be set up is released or unlocked, as it normally would be when a key is depressed, segment 345 will now be free to be rocked counterclockwise under the action of a tensioned spring 354 connected to the plate 347 and the upper end of the contact pawl 350 will pass through the aligned slots 336 and 340 of each pair of bars 335 and 339 in the related first column until said pawl abuts the tooth 341 of a bar 339 which has been shifted and has been retained in shifted position due to the maintained closure of the holding circuit of the magnet 323 which caused the bar 339 to be shifted.

Contact pawl 350 will now abut the tooth 341 of the actuated bar 339 in the first column and as the pawl strikes the tooth 341 it will rock clockwise about its pivot 349 as segment 345 rocks counterclockwise about the center of shaft 346. Due to the line of travel of the end of pawl 350 it will rock slightly upwardly to make contact with the side of the movable digit bar 339 above notch 340. Spring 354 will urge the segment downwardly until extension 352 strikes a pin 355 carried by the plate 347 at which time the unit comes to rest with pawl 350 resting against and above a tooth 341. In this manner the segment 345 is definitely stopped at a differential position with the contact pawl 350 making an electrical contact with the digit contact bar 339 which has been shifted. After this electrical contact has been made the holding circuit for the magnet 323 is broken and the slideable bar 339 will now be retracted by means of the interconnected spring 356 (Figs. 29 and 30). Contact pawl 350 is now out of engagement with tooth 341 and in alignment with a slot 340 but due to the upwardly rocked position of pawl 350 it will remain in a position against the top side of bar 339 but is out of the slot 340, even though the previously shifted bar 339 comes to normal. This position of pawl 350 prevents an interference with the next shift of bar 339 to set up the same digit in another column. The electrical digit readout circuit from a digit bar 335 extends from said bar through the contact pawl 350, the metal plate 347, spring 354, and spring clip extension 358 which terminates in a plug socket 359. The plug sockets 359 (see Fig. 29) are carried by a bar 357 of insulating material and these are the column plug sockets 1-80 for the 1-9 digit setup.

In view of the fact that an alphabetic or combinational setup in a column also requires a 0, X, R setup, means is provided under control of the 0, X, R magnets 323 to effect a 0, X, R setup in another portion of the storage unit. To this end a somewhat similar arrangement is provided and consists of a segment 360 (Fig. 26) which is rocked by a spring 361 about a rod 362 so that a contact pawl 363 will make contact with the pairs of 0, X, or R setup bars 364, 365, 366, respectively. The springs 361 are connected to separate plug sockets 367 to split the readout for digits 1-9 and 0, X, R in each column.

From Fig. 26 it will be observed that an extension 368 of segment 345 abuts an extension 369 of segment 360. This interconnection is provided to

22

start the movement of contact pawl 363 through the 0, X, R digit bars when the contact pawl 350 of the related column starts its movement through the digit bars 1-9. If there is no setup on the 1-9 portion of the readout, segment 345 will go to its extreme rocked position so that segment 360 can go to any desired 0, X, R position.

It is explained that if there is no setup in a column the rocking of a latch lever 375 will enable both segments 345 and 360 to go to their extreme rocked positions which will happen when a column spacing operation is effected under control of a space bar on the keyboard, or by other controls to be subsequently explained.

It is further explained that a single step of plate 347 and extension 368 will be sufficient to release lever 360 to the selected 0, X, R position. This may be effected because of the ratio of extensions 368, 369 with respect to their centers on shafts 346 and 362.

It is desirable that the operator be apprised of the numerical setup in each column and for alphabet data the numerical part of the setup and to this end each segment 345 carries a plate 370 having a pointer 371 (Fig. 27). The radial position of the plate 370 places each pointer 371 aside of a digit 1-9 on a nearby digit scale 372 (Fig. 24). This indication will enable the operator to verify the numerical setup in each column.

Each segment 345 is normally held in latched position by a latching lever 375 (Fig. 27) which is pivoted upon a rod 376 and urged by a spring 377 so that the lower end of the latching lever 375 engages a step 378 of the related segment 345. Each latching member is rocked to unlatch the segment 345 concomitantly with the depression of each key and, therefore, as the keys are successively depressed, the latching levers 375 are rocked in succession, from column one to column eighty, unless some columns are skipped. Associated with each latching lever 375 is an interposer 379 slidably mounted on a rod 380 and biased downwardly by a spring 381 so that normally a shouldered extension 382 of the interposer 379 will hook under stationary bar 383. All of the interposers 379 are normally latched in the position shown in Fig. 27 except the interposer 379 associated with the first column which is to be set up. This, however, is not necessarily column one. As will be subsequently explained, the interposer of the first column to be set up is not latched in the position shown in Fig. 27 but will be shifted by its biasing spring 381 so that normally an extension 384 thereof is interposed between a bail plate 385 and an extension 386 of the associated latch lever 375. By means to be presently described, each depression of a numeral or alphabet key will cause the bail 385 to be raised upwardly and this will cause the rocking of the latch lever 375 of the first column to be set up counterclockwise against the action of the spring 377, thus disengaging the latch lever 375 from the step 378 to unlock the segment 345. Contact pawls 350 and 363 now take their differential positions, depending upon the stop bars which have been shifted.

Associated with the latch 375 of each column, with the exception of the latch in column eighty, is a transfer member 387 pivoted upon a rod 388 and to which the previously mentioned spring 377 is connected so as to cause each transfer member 387 to normally rest upon the extension 386 of the latch lever 375. Each transfer member 387 is bent at 389 to have its forward extension 390 overlie and rest upon a shoulder 391 of the interposer 375 of the next higher numbered

column. Hence, it is obvious that when a latch lever 375 is rocked to release the segment 345 of one column, say column one, the cooperation of the extension 386 with the associated transfer member 387 will rock the latter clockwise as viewed in Fig. 27, causing extension 390 in cooperation with shoulder 391 to rock the interposer 379 of the next higher column, or column two, so that its shoulder 382 thereof will be disengaged from the stationary bar 383. This disengagement enables the biasing spring 381 to shift this interposer and it is now in such position that the next upward elevation of the bail 385 concomitant with the next key depression will cause the latch lever 375 of the related column to be rocked to release the associated segment 345. Hence, it is obvious from the above that when a latch lever 375 of one column is rocked to release a segment 345 it also causes the interposer 375 of the next column to be set up to be positioned for operation by bail 385 to cause upon the next key depression the rocking of the associated latch lever 375.

Reference has been made to the bail 385 and from Fig. 31 it will be seen that bail 385 underlies the series of interposers 379 and is carried by arms 393 which are loosely pivoted on the rod 380. The yoke portion which is pivoted upon the rod 380 has integral extensions 394 to which links 395 are connected. Each link, as best shown in Figs. 27 and 28, is connected to an arm 396 secured to a rock shaft 397. To rock shaft 397 the arrangement shown in Fig. 28 is preferably employed. Referring to this figure, there is provided a space magnet 398 which is energized upon the operation of the keys of the keyboard as will be subsequently explained in connection with the diagram. Energization of the magnet 398 (which will be known as the space magnet) will attract its armature 399 and through a link 400 will rock a latch 401 from a cam 402, permitting a spring-pressed lever 403 to move the cam 402 against the periphery of a continually rotating roller 404. The cam 402 is rotated by contact with the roller 404, causing the carrier plate 405 of the cam 402 to rock counterclockwise about rod 406 as viewed in Fig. 28 and then clockwise. The carrier plate 405 is pivoted on said rod 406 and has a link connection 407 to an arm 408 secured to the rock shaft 397. The aforementioned arrangement is of a well known construction and is employed in a typewriter known commercially as the "Electromatic" and is fully shown and described in Patents Nos. 1,777,055 and 1,873,512. This arrangement is known as a "cam unit" and will be so called herein. Such cam units can be operated either by a magnet, or related keys.

Reference has been made to the continuously rotating roller 404 which is secured to a continuously rotating shaft 409 and from Figs. 24 and 25 it will be seen that to shaft 409 there is secured a gear 410 which is driven by a gear 411, secured to a drive shaft 412 through an idler gear 413. Referring to Figs. 2 and 5 secured to the constantly rotating drive shaft 78 is a bevel gear 414 in mesh with a bevel gear 415 secured to a shaft 416 which carries a bevel gear 417 in mesh with a bevel gear 418 secured to shaft 419. To shaft 419 there is secured a bevel gear 420 (Fig. 1) in mesh with a bevel gear 421 carried by the shaft 422. The lower end of shaft 422 carries a bevel gear 423 meshing with a bevel gear 424 secured to the shaft 412. This constitutes the connection between the main power drive and the constantly rotating roller shaft 409 of the storage unit. In-

cidentally it is about shaft 422 that the storage unit is rocked to operating position as in Fig. 1, or into the cabinet at the right side of the machine.

5 The manner in which the setup in the columns of the storage unit controls the punching mechanism will also be explained in connection with the wiring diagram but, in general, for automatic punching, when interposer 379 of column eighty 10 is elevated upwardly by the bail 385 a pin 375 (Fig. 26a) carried thereby will elevate the lower blade of contacts 598 to close a circuit to energize LCM clutch control magnet 61 (Fig. 4) and UCM clutch magnet 21 (Fig. 3), initiating the operation of 15 both card feeds and the punching mechanism. Also, as will be described in connection with the wiring diagram, an emitter will transmit differentially timed impulses to the 9-1 digit bars 335 in this named order and thereafter to bars 0, X, R in this latter named order. These impulses are timed with the passage of the corresponding index positions of the card past the punches and impulses from the bars which are contacted by the pawls 350 or 363 will be directed by the 20 previously described electrical connections to plug sockets 359 or 367 and from such sockets by plug connections to the punch selecting magnets 173 of the card columns in which punching is to be effected. After the punching operation the 25 setup for both the digits and 0, X, R sections of the columns which are to be reset are reset in a manner now to be described.

Resetting of columns in storage unit

35 It is desirable to manually or automatically reset those columns which have been employed to control card punching operations and which are not to be utilized a second time (as in gang punching) and to also restore a selected group of columns in case an error has been made in the setup. It will be explained in the beginning the manner in which the segments 345 are restored from differential positions to normal shown in Fig. 26. Associated with each of the segments 345 is a resetting member 435 slidably mounted on a rod 436 (Fig. 27) and having a rearward portion 437 (Fig. 26) which is in the plane of a stud 438 carried by the related segment 345. A biasing spring 439 (Fig. 27) normally retracts the resetting members 435 to the position shown in Fig. 27 to cause an upper edge 440 to coact with a finger 441 of a related member 497 which is now stationary at this time. Each group of five members 435 has an associated bail 442 which coacts with depending portions 443 of said resetting members 435. According to the differential positions of the segments 345 the studs 438 will be at differential distances from the rearward operating portion 437 of each resetting member 435 and the rocking of the bail 442 to the left as viewed in Fig. 27 will cause each member 435 to be shifted to the left to cause contact between the operating portion 437 thereof and the related stud 438. This will restore each segment 345 clockwise, causing the related contact pawl 350 to slide through the aligned slots of the digit bars 335 and 339 to occupy the position shown in Fig. 27 where the segment 345 will again be latched by the related lever 375. The extension 368 of the segment 345 will coact with the extension 369 of the segment 360 and also restore the contact pawl 363 to the normal position shown in Fig. 26.

Various ones of the interposers 379 have also been unlatched from bar 383 and are now in their rearward left hand position and these are also

returned to their normal position to be relocked by the bar 383. Each resetting member 435 carries a pin 444 in the plane of a tail 445 of a double arm 446 pivoted on a rod 447, said arm 446 coacting at the upper end with a notch 448 formed in the rear underside portion of the associated interposer 379. The pin 444 of each member 435 will coact with the tail 445 to rock the double arm 446 clockwise about the rod 447 and by engagement with the shouldered notch 448 will restore all interposers to the right to again be relocked by the bar 383, provided the related member 497 is in the Fig. 27 position. At the same time the interposer 379 of the first column to be set up is rocked by an extension 385a (Fig. 31) of bail 385 to be unlatched from bar 383 so that it will be in a left hand position with extension 383 between bail 385 and extension 386 to thus release the segment 345 of column one upon the next keyboard operation when bail plate 385 rocks the related latch lever 375.

However, column one is not necessarily the first column to be so conditioned because, as will appear later on, the information in certain columns may be retained set up under control of a perforated card. In this case one or more slides 497 (Fig. 27) are latched down so that fingers 512 thereof will rock related interposers 379 clockwise about shaft 380 to unlatch them from the bar 383. Assuming that the first five interposers related to the first five columns which ordinarily would be set up are so unlatched they will be drawn to the left by springs 381 so that their extensions 384 are between the bail 385 and the extensions 386 of levers 375. An automatically transmitted impulse to the space magnet 398 will, as previously described, rock bail 385 and the upward motion of the bail 385 will thus rock the latch levers 375 of columns 1-5. The extension 386 of the latch lever 375 of column 5 will rock the double arm 387 and by the cooperation of extension 390 with the shoulder 391 of the interposer 379 of column 6, the latter will be rocked to unlatch it from the bar 383. Thus, the interposer 379 of the first column to be set up is unlatched but due to the upward position of the bail 385 it cannot move to the left as viewed in Fig. 27 until said bail moves downwardly. This will free such interposer for movement to the left by its spring 381 so that its extension 384 is now over the bail 385. Thus, latch lever of column 6 will be rocked upon the first setup operation of the machine and columns 1-5 are automatically skipped.

As will be later described, such conditioning of the first five columns will also prevent resetting of the information therein.

The reset bail 442 alluded to is not a single bail which is common to the eighty resetting members 435 but consists of sixteen individual bails 442 which are shown in Fig. 32 and the provision of sixteen bails, that is, one for each five resetting members 435 enables the manual resetting of the segments 345 and 360 in selected groups of five, or the resetting of the eighty segments 345 and 360 by the machine if so desired.

One type of reset operation is to reset all of the segments 345 and 360 after a card punching operation and this manner of reset will now be described. Each of the bails 442 is pivoted on a rod 449 (Fig. 27) and one side arm thereof has a depending integral extension 450 which carries a pin 451 engaged by an open notch 452 of a link 453 slidably mounted on a rod 454. The

series of links 453 are shown in Fig. 32. A bail 455 is rocked to effect the rocking of all of the sixteen bails 442 whereas a bail 456 is utilized to rock only selected bails 442.

Reset of all columns of storage unit

In this operation the bail 455 is employed and from Fig. 27 it will be seen that its rearward edge coacts with a substantially vertical ledge 457 of each of the sixteen links 453. Bail 455 has a link connection 458 (see Fig. 32) similar to the link 407 shown in Fig. 28 and said link is connected to a member 459 similar to member 405 of Fig. 28. Member 459 is a carrier member for a cam unit similar to the cam unit shown in Fig. 28 and previously described. The Reset magnet cam unit (see Fig. 32) may have a selective clutch connection to the constantly rotating roller 404 under control of a reset magnet 460 shown only in the wiring diagram in Fig. 27d.

In the mode of operation of the machine where the storage columns are automatically cleared after punching, an impulse is automatically transmitted to the reset magnet 460 at the termination of card punching operations to effect the operation of the cam unit and the rocking of the member 459 to move link 458 to the right (Fig. 32) and thus rock the bail 455. Bail 455, coacting with the edges 457 of all sixteen links 453, will shift all links to the right and since they each have a pin and notch connection 451-452 to the depending extension 450 of the related bail 442, each of the latter will be rocked to reset all of the five associated segments 345.

This provides for the automatic reset of all columns if the machine is set up for automatic reset. As will be described later in connection with the wiring diagram, the depression of an error reset key 616 (Fig. 17a) on the keyboard will cause the energization of the reset magnet 460 and resetting for all columns will be effected in the same manner.

Selective reset for correction purposes

It is desirable at times to correct errors in columns which are discerned by examination of the indicator devices shown in Fig. 24 without, however, resetting all of the previously setup columns which have been found correct. It has been found that a desirable and efficient way of correcting errors is by resetting only five columns which include the column in which an error has been located. This sectionalization of resetting operations is effected by means of sixteen keys 461 (Figs. 1 and 28) mounted on the top of the storage unit and accessible for operation by the operator. The operator knows from experience which key will cause resetting of the five columns in which an error has been made and accordingly depresses that particular key. Each key 461 is slidably mounted in a cover plate 462 (Fig. 28) and is articulated to a double arm 463 pivoted on a rod 464 and drawn by a spring 465 so that each key is in its normal upward position. The forward end of each double arm 463 has a link connection 466 to the related link 453. Obviously, from Fig. 28 the depression of a particular key 461 will elevate its link 466 and thus rock the related link 453 about the rod 454 so that the operating edge 451 (Fig. 27) of the link is now in operative coaction with the bail 456 which, likewise, extends the width of the machine and, therefore, may coact with any rocked link 453. Bail 456 has a link connection 467 (Fig. 32) connected to a plate 468 similar to the plate 405

(Fig. 28) and which is therefore actuated by the Reset keys cam unit (see Fig. 32). This cam unit is mechanically made effective by the depression of each key 461 by virtue of a bail 469 which, as shown in Figs. 24 and 28, extends over all the double arms 463 and hence said bail 469 is elevated upwardly by the depression of any key 461. Bail 469 has a depending link connection 470 (Figs. 24, 28, and 32) to render the cam unit effective, it being obvious from the previous description that the elevation of link 470 will render the cam unit effective to rock the bail 456 and thus shift the rocked link 453 engaged by said bail 456 to the right. This, as previously described, will cause the associated bail 442 to be rocked forwardly and reset the five segments 345 and 360 associated therewith.

Card control for retaining data setup by preventing resetting of selected columns

In the normal operation of the machine all of the sixteen bails 442 are operated by bail 455 after the card punching operation to reset all columns. It is desirable to have the machine selectively arranged so that the setup in certain columns may be retained after the initial setup, eliminating the necessity of the operator to repeat the data setup in the storage unit for each card punched. In the present machine this suppression of resetting in selected columns is under control of a card which can first be punched by the machine in a plurality of columns at the X, 1, 3, 5, or 7 rows. A plurality of perforations in a desired row which represents a card field will prevent the resetting of the corresponding columns of the storage device. In the following example it is assumed that these fields represent controls for columns set up to represent the minor group classification, the intermediate group classification and the major group classification, which are well known as group control in card controlled accounting operations. Perforations may also be made at rows 5 and 7 to suppress resetting of other columns of the storage unit and are designated as "select skip" and "skip," in view of a skip function. In all columns where the setup is retained, such columns are skipped so that the operator can disregard such columns and merely effect the successive key depressions to set up the desired columns, the arrangement being such that columns in which reset suppression is called for by a control card are automatically skipped. The control perforations and their meanings are designated below:

- "X" row—Minor group
- "1" row—Intermediate group
- "3" row—Major group
- "5" row—Select skip (with key control)
- "7" row—Skip

The arrangement for effecting this control will be described in connection with Figs. 27, 28 and 32.

The card used for control purposes is of the same type as is punched by the card punching mechanism and, in fact, this control card may be punched by setting up the desired X, 1, 3, 5 or 7 digits in the desired columns of the storage unit under control of the keyboard and then causing a card to be punched under control of the storage unit. The punched card is removed from the hopper and is inserted in a card slot 675 (Figs. 24, 27, and 28) of a card guide member 676 which is at the top of the storage unit and accessible to the operator. The card is disposed with the

printed face of the card in view of the operator and with the 9 index points at the bottom. In such position of the card the columns numbered one to eighty will be correlated with the reset suppression devices for corresponding columns of the storage unit. The inserted control card passes between fixed guide plates 471 and 478 (Figs. 27, 28) which have horizontal rows of apertures in alignment with the X, 1, 3, 5 and 7 rows of card. Through such apertures in guide plates 471 and 478 analyzing pins 479 project. The analyzing frame consists of an analyzing pin box which is normally in such position that all of the analyzing pins 479 are out of engagement with the apertures in guide plate 471 so that the card may be freely inserted. The pin box consists of a pair of end side frame plates 480 (Fig. 28) and 481 (Fig. 27) which are cross connected by a plurality of bars 482 and said bars have attached thereto guide plates 483 and 484 in which are slidably mounted the five rows of analyzing pins 479, each row having eighty pins. Each of the side plates 480 and 481 is supported at each end by an arm 485 (Fig. 28) loosely pivoted on a support rod 486. Attached to each side frame plate 480 and 481 by screws 488 (Fig. 28) there is a plate 487. Pivoted on a shaft 491 are arms 490 which carry a rod 489 passing through the plates 487. The pin box is thus supported at each end by a parallelogram arrangement and the rocking of the rod 489 in one direction or the other will move the pin box in substantially a horizontal straight line movement to project the rows of pins 479 against the surface of the control card. The means for moving the pin box to analyzing position is performed manually and consists of an externally operated rod 492 (see Fig. 1) supported by a pair of bell cranks 493 (Figs. 24 and 25) which are pivoted at 494 to the metal side frames of the storage unit. The rod 489 has a link connection 495 to the related bell crank 493 and said rod 489 works in a clearance slot 496 formed in each metal side frame plate of the storage unit. Grasping the rod 492 by the hand and moving it in one direction or the other will move the analyzing frame into or out of analyzing position. In the position of the rod 492 in Fig. 25 the pin box is out of analyzing position and when moved rearwardly, or to the left as viewed in Fig. 25, bell cranks 493 will shift links 495 and rod 489 to the left to position the pin box frame to the analyzing position shown in Fig. 27. This movement of the pin box will force the five rows of pins against the surface of the card and where a pin finds a hole it will pass through the card hole and the plate 477, as is shown in Fig. 27 for the X pin 479.

Associated with each vertical row of pins and therefore each vertical column of the card in which the index points X, 1, 3, 5 and 7 are, is a control slide 497, there being eighty of these slides, as is shown in Fig. 32. Said slides are slidably mounted in slotted guide bars 498 and 499 (Figs. 27 and 28) and are provided with five shoulders 500, each shoulder cooperating with the pin 479 in the related column and row. Normally each control slide 497 is kept elevated by a spring 501 so that each shoulder 500 is above pin 479 so as not to obstruct its line of travel. Each control slide 497 has a foot portion 502 and cooperating with said portions of the eighty slides 497 is a transverse bail plate 503 secured to a rock shaft 504. The means for rocking this shaft will be subsequently explained, it being noted for the present that this shaft is rocked counterclockwise at the end of the cycle after the card punching

on the first detail card has been completed and just before balls 442 are moved to reset the columns of the storage unit. Of course, the control card is always inserted before a card punching operation so that after punching the first card selected columns will be retained set up. Rocking of bail plate 503 will draw the control slides 497 downwardly and wherever there is a pin 479 projected, due to a hole in the card, the control slide 497 will shift such pin to the right against the action of a spring 505, of which there is one for each pin. As the shoulder 500 passes by the pin the spring 505 will reversely project the pin 479 to the left above the shoulder 500, thus causing the slide 497 to be latched down by the projected pin. Of course, in orders where there is no pin 479 projected, the control slide will merely be moved upwardly or downwardly without being latched.

When each control slide 497 moves downwardly the extension 441 thereof now being in contact with the top edge 440 (Fig. 27) of the resetting member 435 will rock said member clockwise about the rod 436 and the arcuate edge 506 (Fig. 27) will cooperate with the cross plate of the related ball 442. If a slide 497 has not been latched down it will return and enable the resetting member 435 to return to the position shown in Fig. 27 and resetting of the related column will not be suppressed. However, if the control member 497 is latched downwardly it will rock and retain the resetting member 435 in such angular position that the operating portion 437 will not strike the stud 438 of the associated segment 345 as it is rocked by its bail 442, and segments 345 and 360 will not be reset, and the setup in this column will be retained. This prevention of resetting will be retained as long as the control card remains in analyzing position. While the operation has been described in connection with the X row of perforations, the operation is the same for other rows. It is pointed out that the prevention of resetting for the same column can be effected by a perforation in the corresponding column of the card at either the X, 1, 3, 5 or 7 row, since the control action by the slide 497 on member 435 is similar. The reason for having a plurality of rows for control purposes will appear later.

The rocking of the shaft 504 is effected by means of a cam unit designated "Control bail 533 cam unit" in Fig. 32 and similar to that previously described. This cam unit is controlled by a magnet 508 which is energized by circuits to be described in connection with the wiring diagram of Fig. 37d. The cam operated plate 510 (Fig. 32) of this cam unit has a link connection 509 (Figs. 28 and 32) to an arm 511 (Fig. 28) secured to the rock shaft 504 to which, as previously, the control bail plate 503 is secured.

Skipping of columns of storage unit where setup is retained

It is obvious that since the resetting of selected columns of the storage units is suppressed by the control card, the setup in such columns should be disregarded by the operator in the operation of the keyboard. In other words, in an assumed example, if the resetting of columns 3, 4 and 5 is suppressed and the setup is retained, immediately after setting up column 2 of the storage unit the next key operation should cause the setting up of column 6. Such column skipping operations are effected by the latched control slides 497 of

the columns in which resetting is suppressed and, therefore, for each column of the control card where there is a perforation in any row the corresponding column of the storage unit will be automatically skipped.

Each control slide 497 is provided with a finger 512 (Fig. 27) which is in the plane of the right hand extension of the interposer 379 of the same order. It will be recalled that prior to a card punching operation, which may be an operation of the machine to set up a suppression-reset condition under control of a control card, the ball plate 533 is rocked to move all control slides 497 downwardly and in the assumed example, if the control slides 497 for columns 3, 4 and 5 are latched downwardly, due to perforations in columns 3, 4 and 5 of the control card, they will rock the interposers 379 of the same order out of engagement of the latching bar 383, if they are in the Fig. 27 position, and will prevent the interposers 379 from being latched on the bar 383 when they are restored to the right by double arms 446. After the card punching operation the interposer 379 which is in the column at the left of the columns which are to be skipped is returned by the arm 446 so as to be relatched on the bar 383 and in the assumed example this would constitute interposer 379 for column two.

As best shown in Figs. 27 and 31, each interposer 379 has an offset portion 514, each of which is in the plane of an upward extension 515 of the interposer of the next lower order. When such lower order interposer, which is column 2 in the assumed example, is returned to the right, its extension 515 cooperating with the lateral extension 514 of the next higher order interposer will return column 3 interposer to the normal position shown in Fig. 27 but the finger 512 of the latched control slide 497 will hold it downwardly so that it cannot be relatched on the bar 383. In the same way the column 3 interposer will shift column interposer 4 to the right (Fig. 27) and column 4 interposer will shift column 5 interposer to the right. The column 6 interposer is not under the action of a control slide 497 and it will be relatched on the bar 383. Thus, the interposers 379 for columns 2, 3 and 4 are in the position shown in Fig. 27 but are not relatched on bar 383. In the next two keyboard operations columns 1 and 2 are set up in succession and immediately upon column 2 interposer being rocked by ball plate 385 to be unlatched from bar 383 its extension 515 in cooperation with offset 514 of column 3 interposer will enable this interposer to also be shifted to the left as viewed in Fig. 27. The interposers for columns 4 and 5 will similarly move to the left hand position. Column 6 interposer will remain latched on bar 383.

Upon the key depression for setting up column 2 bail 385 will rock the interposer 379 for column 5 and through the transfer member 387 the interposer 379 for column 6 will be unlatched from the bar 387 and hence this interposer will be effective to rock the latch lever 375 for column 6 upon the next key depression. Even though the latch levers 375 related to columns 3, 4 and 5 are rocked in this operation, this is ineffective because of the retained set-up for such columns.

In the above manner, columns of the storage unit corresponding to perforated columns of the control card, in any row, are automatically skipped without the attention of the operator and such skipping operations are under control of the 75 latched control slides 497.

Means to nullify suppression of reset required by control card

It is sometimes desirable to enable another setup of columns of the storage unit which are required to be retained set up, due to the suppression of reset control called for by the control card. This is effected under control of special keys on the keyboard, each having connecting control means whereby the suppression of reset control required by the control card for certain rows is nullified, at the will of the operator.

Referring to Fig. 27 each analyzing pin 479 has a rectangular notch in which fits a cross bar 516 and each cross bar is common to each horizontal row of pins 479. Each cross bar 516 is pivoted on a rod 517 carried by the side end plates of the pin box. Attached to one end of the cross bar 516 is a plate 518 which has connected thereto a depending link 519 which is suitably guided in a slotted plate 520.

The lower end of each link 519 carries a pin 521 and overlying each pin 521 is a finger 522 which is an integral portion of an arm 524 loosely pivoted on the rock shaft 523. Since there are four transverse bars 516 used herein there are four depending links 519 and four arms 524 with their connecting links 525. These four links 525 appear in Fig. 32 and each has a connection to a related cam plate 526, similar to the plate 405 previously referred to. Each cam plate 526 is rocked by a cam unit actuated under control of an individual electromagnet (similar to magnet 398) and these magnets appear in the wiring diagram and are designated 527, 528, 529, 530 and the energization of each of these magnets is under control of a related key on the keyboard.

Assuming that a control card is in analyzing position and requires the suppression of reset of certain columns and that the operator desires, nevertheless, to have such columns reset, the desired key of the keyboard is operated to actuate the cam unit and operate the bar 516 pertaining to the field of columns of the storage unit in which another setup should be made. The rocking of each bar 516 will retract the associated pins 479 to disengage them from the shoulder 500 of the latched down slides 497 pertaining to such columns. This will cause fingers 512 to be raised upwardly to normal position (Fig. 27), permitting the unlatched interposers 379 of such orders to again be latched on bar 383. The elevation of the finger 441 will, of course, permit reset members 445 to again occupy normal resetting positions. Thus, the columns referred to may again be set up to represent new digits or characters.

As will be later described, the keyboard control of the major cam unit control magnet 528, the intermediate 530 and the minor 527 are to interconnected that when the major control key is depressed it will energize the major control magnet 528, intermediate 530, and minor 527 so that the three different fields in the storage unit may again be set up irrespective of the suppression of reset of the control called for by the control card. The depression of the intermediate control key causes a reset of the minor and intermediate fields of the storage unit, whereas depression of the minor control key enables only resetting of the correspondingly designated field. The select skip control magnet 529 is energized under control of a Select skip key on the keyboard. There is no bar 516 for the seventh row

of pins 479 and the control exercised by the perforations in this row cannot be nullified. The manner in which the above described intercontrol is effected will be made clearer in a description in connection with the wiring diagram.

Keyboard

The keyboard will be described with reference to Figs. 17a, 33-36, inclusive.

10 Each of the keys comprises a key stem 535 slidably mounted in a top guide plate 536 and a bottom guide plate 537, and attached to the upper end of each key stem is a key cap 538 bearing indicia representing the character designated by the key or the function effected under control of such key.

One series of keys 585 comprises those designated 1-9, 0, X and R and each of said keys is adapted to close a single set of contacts. As best shown in Figs. 33 and 34 for the "2" key, the stem 535 of said key has a shoulder 539 which cooperates with one arm of a bell crank 540, one arm of which fits in an open notch 541 of a slide 542. Said slide 542 carries a contact operating bar of insulation 543 having studs 543a and 543b abutting a spring contact plate 544.

When the key is depressed it will rock the associated bell crank 540 clockwise shifting slide 542 to the left and tensioning a return spring 545 (Fig. 33). Contact closing bar 543, now having moved to the right, will enable the spring 544 to move in the same direction by its inherent resiliency to close contact terminals 546a and 546b. Such terminals comprise contacts designated 586 in the wiring diagram. In this manner each of the aforesaid keys close a single set of contacts 586.

The alphabet keys 587 are arranged in three rows in the same manner as in a conventional typewriter. The associated contact operating mechanism is the same as previously described except that they are adapted to close two sets of contacts designated 588 in the wiring diagram.

Each of the keys 1-9, 0, X, and R and all of the alphabet keys of the keyboard are adapted to close contacts 590, designated as "bail contacts" in the following manner:

The slides 542 operated by each of said keys have upward projections 547 which abut a transverse bail 548 carried by arms 549 loose on a support shaft 550. To one support arm 549 there is connected by a pin 551 a pitman 552 having a shoulder 553 normally resting upon an extension 554 of the left hand contact blade of contacts 590. Therefore, each of the aforesaid keys when depressed will rock bail 548 to the right, drawing pitman 552 to the right and by the engagement of shoulder 553 with contact extension 554 will close contacts 590. In order to prevent repeat operations which could be effected by retaining a key depressed, independent means is provided to open contacts 590 at a timed operation in the machine. At such timed operation an impulse is transmitted to trip magnet 597 (Fig. 33) which attracts its armature 555 and through an interconnecting link 556 a bell crank 557 which carries a pin 558 beneath the pitman 552 is rocked clockwise so as to elevate the pitman 552 and disengage shoulder 553 from contact extension 554. The resiliency of the shifted contact blade will now cause it to return to normal position to open contacts 590.

Also mounted on the keyboard are keys designated Start and Stop which are shown in Fig. 36. The depression of the Stop key opens contacts 599 whereas the Start key when depressed closes Start key contacts 584 in an obvious manner. The

key 608 designated Dual key and a key 616 designated Error reset are adapted in the manner previously described to close an associated single set of contacts whereas the Minor key 612, Intermediate key 613, Major key 614, and Select skip key 615 close a dual set of contacts. All of these keys 608, 612-616 when operated are adapted through their slides 542 to rock a bail 558 (see Fig. 35) about a pivot 560. The bail 558 extends transversely in front of the ends of the slides 542. Said bail has a rearward extension 561 which closes bail contacts 610. The function of these contacts will be described later. Also on the keyboard there is a Space bar 562 secured to a rod 563. Attached to one end of the rod 563 is a contact operating plate 564 which is adapted to close contacts 566 when the Space bar is depressed.

At the rear part of the keyboard, as best shown in Fig. 17a, there is a series of lever operated switches 567. Each of said switches has an associated name plate indicating the function of the switch. These switches are of well known construction and close either single blade or dual blade contacts.

Wiring diagram

The operation of the machine will now be described in connection with the wiring diagram of Figs. 37a-37d and the timing diagram of Fig. 10a.

Prior to running the machine a stack of cards is placed in the supply hopper 28 (Fig. 1), and the manually operated Motor start switch 583 on the keyboard (Figs. 17a and 37a) is positioned to close its contacts and by an obvious circuit in Figs. 37a it will connect the motor M across power supply lines 580, 581. The Start key on the keyboard is then depressed to close its contacts 584 (Fig. 37a). Across the lines 580 and 581 are cam contacts CR5 in series with a relay R27 which is energized when such contacts close. At this point it should be understood that as is customary in machines of this type constantly running cams driven by the continually running shaft 78 herein close contacts CR1-CR5 (Fig. 2). Also a series of LC1-15 cam contacts is provided and these are operated by cams driven by shaft 99. Also contacts MCCR1, MCCR2 cam contacts are operated by continually rotating cams which rotate with the continuously rotating ratchet wheel 258 (Fig. 3). All of these contacts have their timing designated in Fig. 10a.

CR5 cam contacts pick up the R27 relay a plurality of times in the cycle and with the Start key contacts 584 closed at one of such times a circuit will be closed from line 580 through the contacts 584, R27a relay contacts, R26 relay to line 581. A hold circuit will be extended through the R26b relay contacts through LC15 cam contacts now closed back to line 580. Closure of the R26a relay contacts will close a circuit from line 580 through R26a relay contacts, LC9 cam contacts now closed, R1a relay contacts now closed, MCCR1 cam contacts now closed, normally closed R18b relay contacts to LCM clutch magnet 61. The clutch controlled by this magnet shown in Fig. 4 will be engaged to operate the card punching mechanism and drive the shaft 99 a complete revolution, and the LC cam contacts will close by cams on this shaft at times according to the timing diagram of Fig. 10a. When LC7 cam contacts close (Fig. 37a), a circuit will be made from line 580 through LC7 cam contacts, dual card switch lever contacts 1 now closed, UCM clutch control magnet 21, to line 581. The upper clutch

(see Fig. 3) will now be engaged and the first card will be fed to the visible reading station. The Start key is again depressed to feed following cards and the first card in a position to enter the punching mechanism. The keyboard controlling the storage unit is now operated to set up the desired columns. For manually initiating card punching, another depression of the Start key will cause the upper clutch controlled by UCM magnet 21 and the LCM clutch controlled by magnet 61 to again be engaged or continue to be engaged so that the first card may now be fed from a position ready to enter the punching mechanism through the punching station and a second card will be fed in a position to enter the punching station. The keyboard is now operated to set up the storage unit for punching the second card, and the Start key is again depressed.

In Fig. 37c there is shown diagrammatically the series of keys of the keyboard and their wiring to selectively energize setup magnets 323 of the storage unit. It will be observed that the 0-9, X, R keys 588 close single contacts 586, whereas the alphabet keys 587 each close dual contacts 588. From the setup magnets 323 there are wire connections 589, and the contacts 588 controlled by the 0-9, X and R keys are wired to the setup magnets 323 correspondingly designated. However, for the alphabet keys the dual contacts 588 are connected so as to cause the energization of the setup magnets 323 according to the well known alphabetical code. For example, when the 8 key is depressed it will, through the associated 588-8 line, pick up the 323-8 magnet. The depression of the H key will also pick up this magnet and its extra contact will cause the pick-up of the 323R selector magnet.

The energizing circuit for selector magnets 323 is from the line 580 (Fig. 37c), through bail contacts 590 which are closed upon the depression of any of the setup control keys, through R25b relay contacts now closed, through the respective key operated contacts 586 or 588 to the associated setup control magnet 323, to line 581. It will be recalled that the energization of these magnets will shift the associated bar 339 in either the 1-9 group or the 0, X, R group. Also, when bail contacts 590 close, a supplemental circuit will be extended via wires 591 and 592 to the pickup coil of X relay and also to the space magnet 398 (Fig. 28), both of which are in parallel and each connected to the line side 581. It will be recalled that the magnet 398 effects the reciprocation of bail plate 385 (Fig. 26) to rock the latch lever 375 (Fig. 26) of the column to be set up. It will be remembered that when each setup magnet 323 is energized it will shift blade 330 (Fig. 29) to provide a hold circuit for that magnet which extends through the Xb relay contacts (Fig. 37c) through a cam unit controlled contact CU1, wire 593 back to line 580. The Xa contacts are closed to pick up the hold coil of X relay which is also held through the cam unit controlled contacts CU1. The machine includes a number of these cam unit controlled contacts generally designated CU in Figs. 37c and 37d and their manner of operation is best seen in Fig. 28 wherein it will be seen that operated by each cam unit operated plate (like plate 405) is a depending projection 585 which, in Fig. 28, closes contacts which may be CU3, CU4, CU2A or CU2B of the wiring diagram. By an obvious re-arrangement, the contacts may be normally closed, such as CU1 and opened when the cam unit is actuated. The energization of the space magnet 398 will cause its

cam unit to be actuated and thereby close the contacts CU2A to complete, an obvious circuit to a delay magnet 596. Delay magnet 596 causes a cam unit designated in Fig. 32 to be actuated to close CU2B contacts and open CU1 contacts. Closure of CU2B contacts (Fig. 37c) will complete a circuit if a key should be held depressed, from the line 580, bail contacts 590, cam unit operated contacts CU2B, trip magnet 597, to line 581. As previously described this trip magnet 597 (Fig. 33) will cause the unlatching and opening of the bail contacts 590. Opening of contacts CU1 will break the holding circuit of the energized setup magnets 323 and also the holding circuit for the hold coil of the X relay. The described circuit arrangement provides for the proper sequence of closure of contacts to insure the energization of the setup control magnets 323 as long as is necessary and prevents repeated operations if a key should be held depressed. When punching operations are to be manually initiated the Start key is depressed after setting up the last column of the storage unit to cause a following card to be fed to the punching station and the succeeding card to be punched under control of the storage unit, which is then cleared out, if auto reset switch 603 (Fig. 37d) is in "on" position.

Automatic initiation of card punching

For this type of operation the auto start switch 601a is in "on" position.

When column eighty contacts 598 are closed in the manner shown in Fig. 26a and previously described, a circuit is completed from line 580, through Stop key contacts 599 (Fig. 37a) now closed, through the gang punch switch 600 now in the "off" position, through the auto start switch 601a now in "on" position, through column eighty contacts 598, R27b relay contacts, thence through R24 coil, R25 pickup coil in parallel therewith, to the line 581. By a branch wire 602 the circuit is completed to the R3 coil to line 581. The R24, R25 and R3 coils hold through the R3a hold contacts and cam contacts LC11 now closed back to line 580. The pickup coil of R25P closes the R25a relay contacts (Fig. 37c) completing a circuit from the line 581, the R25H hold coil, through relay contacts R25a, Xb relay contacts, CU1 cam actuated contacts, wire 593 to line 580. R25 relay opens R25b contacts (at the top of Fig. 37c) thereby opening the energizing circuit to the storage unit selector magnets 323 to prevent repeat energization in the event that the key is held depressed.

The closure of relay contacts of R24b and R25d (Fig. 37a) completes a circuit from line 580 through R24b contacts, R25d relay contacts, R26 coil, to line 581. R26 coil holds through R26b relay contacts, LC15 cam contacts, back to line 580.

Closure of R26a contacts will now complete the circuit previously traced to cause the lower clutch magnet 51 to be energized to operate the punching mechanism and cause the feeding of the card which is just ready to enter the punching station to be passed by the punches to receive perforations according to the setup of the storage unit. Of course, LC1 cam contacts (Fig. 37a) will close to energize the upper clutch magnet 21 to feed the following card to the visible reading station.

Punch magnet selecting circuit

Differentially timed impulses are transmitted to the punch magnets 173 (Fig. 37d) to select

5 punches for operation in accordance with the settings of the readout arrangement of the storage unit. These impulses are directed by a circuit from line 580 (Fig. 37d) through circuit breaker contacts LC1, LC2 and LC3, LC4 which have the timing shown in Fig. 10a, thence to the rotating brush of emitter EM. This emitter is of the customary construction and the rotating brush is driven by shaft 99. Impulses in the order 9-1, 0, X, R are sent first to the readout bars 335, 9-1, and are directed through the normally closed RT1-80 contacts, punch selecting magnets 173 to line 581. In accordance with the positions of the contact pawls 350 selected impulses will be transmitted to the punch magnets 173. After the "1" digit impulse has been transmitted, cam contacts LC5 close to energize the readout transfer relay RT to transfer its contacts 1-80 during the time the 0, X, R impulses are transmitted by emitter EM. Thus, the 1-9 readout portion of the storage unit is first read out and then 0, X, R portion and this split readout operation is provided to prevent the possibility of back circuits.

Automatic reset of columns of storage unit

After the reading-out operation the storage unit is automatically reset in all columns where resetting is necessary when auto reset switch 603 (Figs. 17a and 37d) is closed. The circuit for effecting this is from the line 580 through the auto reset switch 603 now closed (Fig. 37d), LC6 cam contacts which close at the end of a cycle after the punching of the card, to the reset cam unit control magnet 460, to line 581. This cam unit closes the CU3 contacts (Fig. 37d) to energize the space magnet 398 to rock ball 385 to effect spacing operations in the storage unit by unlatching interposer 379 of column 1, or the first 40 column to be set up.

Circuit to prevent resetting of selected columns

Also at the beginning of the punch cycle a cam unit designated "Control bail 503 cam unit" in Fig. 32 is actuated by the energization of a magnet 508 to cause the reciprocation of the bail 503 for retaining a data setup by preventing resetting of selected columns of the storage unit in the manner previously described. The circuit extends from line 580, through auto reset switch 603 (Fig. 37d), now closed, LC13 cam contacts, R24a relay contacts now closed, Control bail 503 cam unit control magnet 508, to line 581.

Card ejecting circuit

As previously stated, when the card is in the aligning station it will close card lever contacts 148 (Figs. 13 and 37b), closing a circuit from the line 580 through contacts 148, and R4 and R16 relays to line 581. When the punched card enters the eject station and closes contacts 198 (Figs. 16 and 37a) a circuit is completed from line 580 through R26a contacts now closed, LC8 cam contacts now closed, R3b and R16b relay contacts now closed, card lever contacts 198, to the eject solenoid 199 (see Fig. 14) which renders the card eject mechanism operative to eject the card. When cam contacts LC14 close the stacker solenoid 234 (see also Fig. 18) is energized to cause the card which has been punched to be pushed forwardly in the storage hopper.

Punch selecting circuits under control of master card

75 As previously stated, the machine has pro-

visions for duplicating information under control of prepunched master cards and the electrical circuits for effecting this operation will now be described.

A master card may be used in combination with a setup in the storage unit so that both may control card punching. In this type of operation the master card control switch 604 is in "on" position (Fig. 17a), the auto reset switch 603 is in "on" position, and auto start switch 601a in the "on" position.

Whenever the master card control is to be used the master card control switch 604 (Fig. 17a) on the keyboard is closed, closing an obvious circuit to the R18 relay (Fig. 37b). From Fig. 37a it will be seen that the energized relay R18 opens its R18b contacts and closes its R18a contacts.

When punching is initiated under control of column eighty contacts 598, the R24 relay and R25 relays are energized as previously stated and R24 relay closes R24b relay contacts (Fig. 37a) to complete a circuit from line 580, through R24b relay contacts, through MCCR2 contacts closed at the D position, thence through the R19 relay to line 581. Relay contacts R24b and R25d complete a circuit to R26 relay, as described. R19 relay closes its hold contacts R19a extending a holding circuit through such contacts and LC11 cam contacts back to line 580. Relay contacts R18b now being closed (Fig. 37a) a circuit will be closed from line 580, R26a relay contacts now closed, LC9 cam contacts, R1a relay contacts, MCCR1 cam contacts now closed, through the R19b relay contacts now closed, through master card control contacts 606 now closed, through R18a relay contacts, to the master card unit clutch control magnet 251, and also to the lower clutch magnet 61, to line 581. Energization of magnet 251 will cause the operation of the master card analyzing unit and the analysis of the master card perforations synchronously with the passage to a detail card past the punches and the punch magnets 173 (Fig. 33) will be energized by the following circuit:

From the line 580 (Fig. 37d), through circuit breaker contacts LC1, LC2, LC3, LC4, contact roll 281, master card analyzing brushes 266, plug connections 605 made between selected columns of the master card punch magnets 173 of selected columns, through punch magnets 173 to line 581. If ten columns are punched on the master card, ten plug connections 605 are made to the punch magnets 173 of the desired columns. Each time a detail card is punched the data on the master card will be picked up and automatically duplicated on each detail card.

The plug connections 605 (Fig. 37d) are obviously made to punch magnets 173 of columns which are not controlled by the storage unit. Hence, the corresponding columns of the storage unit are skipped when the manual setup is made. The columns can be automatically skipped by having certain columns of the control card perforated, as previously explained.

Gang punching with source of information from master card and storage unit

Automatic gang punching, that is, punching of a series of blank cards in automatic succession can be effected so that information derived from the storage unit and/or the master card may be duplicated on each card. Prior to instituting such operations the keyboard is operated to set up the storage unit to represent the desired data and obviously this data will be set up in columns

which do not correspond to columns which are to be punched on the blank cards under control of the master card. Since these storage columns are set up once and are not to be reset the auto reset switch 603 (Fig. 37d) is in "off" position. The initial gang punching operations are instituted by retaining the Start key depressed for a number of cycles but automatically thereafter the gang punching operations are automatically continued by supplemental circuits and for this reason the auto start switch 601a (Fig. 37a) is in "off" position. For utilizing the master card as a source of information to be duplicated, the master card switch 604 is in "on" position. The machine is conditioned for gang punching operations by placing gang punch switch 600 (Fig. 37a) to "on" position.

The blank cards in the punching machine are fed automatically one after the other by retaining the Start key depressed until a punched card closes card lever contacts 148 (Fig. 37b) which cause relays R4 and R16 to be continuously energized as long as cards are fed. R4 and R16 close their respective contacts R4b and R16a (Fig. 37a) and when relay R1 is energized by the closure of the LC10 cam contacts to close the R1b relay contacts, a circuit will be closed from the line 580, through Stop key contacts 599 (Fig. 37a), gang punch switch 600 in "on" position, the R4b, R16a, R1b relay contacts all closed, R2 and R17 relays, to line 581. A hold circuit back to line 580 is provided for R17 and R2 relays through the R2a relay contacts and cam contacts LC12, and alternatively through R4b relay contacts as long as cards are being fed to the punching station. When LC12 cam contacts open, R4b relay contacts retain the hold circuit closed.

At the end of a punch cycle cam contacts LC8 close and when MCCR2 cam contacts close, a circuit will be extended from line 580, through LC8 cam contacts (Fig. 37a), R2b relay contacts, MCCR2 cam contacts, R19 relay to line 581. A hold circuit is provided for this relay through R19a relay contacts and cam contacts LC11 which hold the relay energized over to point 7 of the next cycle. Also when cam contacts MCCR1 close at the end of a cycle a circuit will be extended from line 580, through cam contacts LC8, relay contacts R17a, MCCR1 cam contacts, R19b relay contacts, master card control contacts 606 to lower clutch magnet 61, to line 581, and from card lever contacts 606 a branch circuit extends through R18a relay contacts to MCM clutch magnet 251 to line 581. Of course, cam contacts LC1 will pick up UCM clutch magnet 21. Thus, clutch magnets 61, 21, and 251 are automatically energized to cause the machine to continue with successive gang punching operations until the Stop key 599 is depressed which will terminate gang punching operations by causing R2 and R17 relays to deenergize.

It is pointed out that since it takes two machine cycles to operate the master card unit, the master card control contacts 606 will open as soon as the master card moves forward to be sensed by the master card analyzing brushes 266 and contacts 606 will not close again until the card has returned to its home position. Contacts 606 are normally closed by a member 269 (see Fig. 22) and open when member 269 moves to the right, and are not closed until the card has returned to its home position. The opening of these contacts prevents a second impulse from cam contacts LC8 from energizing the clutch magnet 61 after the first cycle of operation. Also

since cam contacts LC7 are not closing no impulse is sent to upper clutch control magnet 21.

Gang punching with source of information from storage unit only

It is possible to condition the machine so that only the data set up in the storage unit is gang punched. For this type of operation the master card switch 604 is in "off" position, the auto start switch 601 is in "off" position, the auto reset switch 603 is in "off" position, and the gang punch switch 600 in "on" position. In this case the impulse circuit from cam contacts LC8 is directed through R17a relay contacts, MCCR1 cam contacts, R18b relay contacts, to the lower clutch magnet 61. Since R18a contacts are open no impulse will be directed to the MCM clutch magnet 251.

Gang punching with source of information from master card unit only

In the present machine it is also possible to condition it so that only master card data will be gang punched. For this type of operation the following switches are in "off" position: auto start switch 601, auto reset switch 603, and both the master card switch 604 and gang punch switch 600 are in "on" position.

The circuit operations are the same as that previously described. It should be noted that due to the normal position of the contact elements 350 and 363 shown in Figs. 26 and 27, no impulses can be transmitted by emitter Em (Fig. 37d) to the punch magnets 173 and the latter will be selected only under control of the master card analyzing unit.

Dual card punching operation—punching initiated by start key, card feed to and from visible station by dual key

In general, by dual card punching operations is meant the conditioning of the machine so that a card (such as an inventory card) may be fed by the depression of a Dual key to the visible reading station and retained there while the operator reads the written data and operates the keyboard to set up the storage unit to represent such data and then by a manually initiated punching operation effected by the Start key causes a card punching operation to punch that card.

This mode of operation involves the use of a Dual key 608 on the keyboard, operable alternately with the Start key. For dual card operations utilizing the Dual key, dual card switch 609 (Fig. 37a) is shifted to the left from the position shown in Fig. 37a. For dual card operations with card punching initiated by the Start key the auto start switch 601a (Fig. 37a), 601b (Fig. 37b) is in the "off" position shown in these figures. Assuming that cards are in the supply magazine, the depression of the Dual key 608 (Fig. 37b) will close a circuit from line 580, through bail contacts 610 (Fig. 37b) which are closed by the depression of the Dual key 608 and other special keys previously mentioned, thence through relay contacts R10a now closed, through Dual key contacts 608 now closed, through the auto start switch 601b now in "off" position, through relay contacts R4a now closed, relay coil R5 to line 581. R5 relay will close its R5b relay contacts (Fig. 37a) closing a circuit from line 580 through Stop key contacts 599, through gang switch 600 now in "off" position, through dual card switch contacts 2, now shifted and closed, R5b relay con-

tacts to upper clutch magnet 21. Engagement of the upper clutch will cause the feeding of the first card from the supply magazine to the visible reading station. The operator will then read the data thereon and operate the keyboard to set up the desired data in the storage unit. After this setup has been completed for all columns, the Dual key 608 is again depressed to cause the second card

5 to be fed to the visible station and the first card 10 previously at the visible station to the punch station. The machine is now in condition for causing the punching of the first card under control of the storage unit and since it is assumed that the auto start switch 601 is in the "off" 15 position, the operator is required to depress the Start key to cause the energization of the R28 relay. The latter closes its R26a contacts (Fig. 37a) which, from the circuit previously described, transmits an impulse to the lower clutch magnet 61 but an impulse to the upper clutch magnet 21 is not transmitted by LC7 because dual card switch contacts 1 are open. This will cause the feeding of the first card past the punches and the latter are selected under control of the storage unit to punch the first card with the desired information. Since the setup in the storage unit is individual for each card the auto reset switch 603 (Fig. 37d) has been closed to automatically clear out the setup in the storage unit. During 20 the feeding of the first card past the punches, the card closes card lever contacts 148 to pick up R4. R4a contacts open to prevent R5 from being picked up if the Dual key is accidentally depressed at this time. There now being a card (the second 25 one) at the visible reading station, the storage unit is again setup under control of the keyboard according to data to be punched on the second card and the Dual key is again depressed to feed the second card to the punching station and the 30 third card from the supply magazine to the visible station. A second depression of the Start key will cause the punching of the second card under control of the setup in the storage unit. These alternate operations of the Dual key to 35 feed cards to and from the visible station and Start key to effect punching are thereafter repeated until all cards are punched.

Dual card punching operation with source of information to be duplicated from master card

In dual card operations it is also possible to utilize the master card analyzing unit so that information from both the storage unit and master card are punched on each inventory card.

55 For utilizing the master card as a source of information to be duplicated the master card switch 604 (Fig. 37a) is in "on" position. It will be recalled that this will cause the continuous energization of the R18 relay and R19a and R19b relay contacts are transferred from the position shown in Fig. 37a. It will also be recalled that in master card control operations the R19 relay is also energized. Therefore, the impulse circuit to 60 the LCM clutch magnet 61 when the Start key is depressed will be directed from the MCCR1 cam contacts, through R19b relay contacts, master card control contacts 606 to LCM clutch magnet 61. An impulse also is directed from the contacts 65 606 through R18a relay contacts to the MCM clutch magnet 251. The energization of the latter clutch magnet will then cause the reading out of the master card perforations and the control of the punching mechanism to duplicate the data on the inventory card.

Card punching operations — punching of card automatically initiated under control of column eighty contact 598

In this type of operation the auto switch 601b (Fig. 37b) is in "on" position which opens the Dual key circuit to prevent the use of the Dual key 608. Auto start switch 601a (Fig. 37a) is now in "on" position to initiate card punching under control of column eighty contacts 598, and the dual card switch 609 (Fig. 37a) is in the position shown.

This operation is substantially the same as that previously described. In starting out, the Start key is first depressed to feed a card to the visible station and then a second depression to feed that card just to the punching station, and a second card to the visible station. The operator then sets up the storage unit under control of the keyboard in accordance with data to be punched on the card which is just at the punching station. When the last column of the storage unit is set up circuits are rendered effective under control of column eighty contacts 598 to cause the feeding of the first card through the punching station, a second card from the visible station to the punching station, and a third card from the supply magazine to the visible station. Data is now set up on the storage unit for punching on the second card, and automatic punching is then effected for the second card when the last column contacts 598 are closed.

Special key operations—circuits controlled by minor, intermediate and major keys

It will be recalled that rows of perforations in selected columns of a control card suppress the resetting of corresponding columns of the storage unit so that such columns may be retained set up. However, data setup in such columns of the storage unit changes from time to time and in order to enable the clearing out of such columns of the storage unit for the setup of new data while the control card remains in position to be subsequently effective, special keys are provided on the keyboard (Fig. 17a) designated Minor 612, Intermediate 613 and Major 614. Prior to setting up the storage unit for a card to be punched with new classification numbers these keys will be depressed to cause clearing out of selected columns, and the keyboard operation will then set up the new data.

Referring to Fig. 37b each of the keys 612, 613 and 614 closes a pair of "a" and "b" contacts (like contacts 588) and upon closure of the "a" contacts a circuit will be closed from the line 580 through bail contacts 610 closed by each of the keys 612, 613, and 614, through R10a relay contacts, through the respective "a" contacts; and the "a" contacts of the Minor key 612 causes the R15 and R23 relays to be energized, the "a" contacts of the Intermediate key causes the R14 and R22 relays to be energized and the "a" contacts of the Major key causes R13 and R21 relays to be energized. One side of each of the above designated relays is connected to the line 581 to complete the circuit. Each of the relays R13, R14 and R15 closes its respective "a" contacts so that a holding circuit for each of said relays and associated relays R21, R22 and R23 is provided through the respective "a" contacts, and R9a relay contacts back to line 580. Each of "b" contacts of the respective keys 612, 613, and 614 also completes an obvious circuit through the R7 relay and the latter is held energized through its R1a

hold contacts, through the R9b relay contacts, back to line 580.

Closure of relay contacts R7b (Fig. 37d) causes a circuit to be closed when the CR4 cam contacts close which extends from line 580, through CR4 cam contacts, R7b relay contacts, the R8 pickup coil, to line 581. The latter closes its R8a contacts and a holding circuit is extended back to the line 581 through the CR2 cam contacts.

10 Referring to Fig. 37d the respective relays R21, R22 and R23 which are energized upon the depression of the respective Major, Intermediate, Minor keys close the respective "b" contacts so that the impulse from CR2 is directed through 15 R8a relay contacts, the "b" contacts of relays R21, R22, R23 to the related cam unit control magnets 528, 530 and 527, respectively. The different cam units actuated by the respective magnets are designated in Fig. 32 and by the actuation of such cam units, mechanisms previously described will come into operation to cause the clearing out of columns of the storage unit called for by the rows of perforations in corresponding columns of the control card. Upon closure of 20 the CR3 cam contacts (Fig. 37d) a circuit is extended from the line 850 through CR3 cam contacts, R8b relay contacts, thence to R9 and R11 relays and the reset magnet 460. R9 relay will open the R9b relay contacts (Fig. 37b) to break the holding circuit of the R1 relay and the energized R12, R13, R14, R21, R22 and R23 relays but after such opening the continued closure of CR4 cam contacts maintains the holding circuit for such relays a little longer in the cycle.

30 In the event that these special keys should be retained depressed, a repeated operation will be prevented by the following circuit: When R11 relay is energized it will close its contacts R11a (Fig. 37b) so that a circuit will be extended from the line 580 through bail contacts 610 which are closed as long as the key is held depressed, through R11a relay contacts, through the R10 relay coil to line 580. The latter closes its R10b contacts to provide a holding circuit extending back to line 580 through bail contacts 610. R10 relay opens its R10a contacts and thus opens the energizing circuit controlled by the special keys.

35 The control magnet 460 which actuates the Reset mag. cam unit is energized under control of the R8 relay as previously described and this will cause the actuation of the cam unit to rock the bail 455 (Fig. 27) to cause the reset of columns of the storage unit which represent the Major, Intermediate or Minor classification numbers.

40 It is preferable to arrange the machine so that when the Major key 614 is depressed the storage columns corresponding to columns perforated in rows X, 1 and 3 will all be cleared out and further when the Intermediate key 613 is depressed it will cause the storage columns corresponding to columns perforated in rows X and 1 to all be cleared out. This is based upon the assumption that a new major classification number has associated new intermediate and minor classification numbers, and that a new intermediate classification number has a new minor classification number. This is effected by the inter-control shown in Fig. 37b where it will be seen that the energization of the R13 relay by the depression of the Major key 614 will close the R13b contacts so as to pick up the R14 and R22 relays. The R14 relay in turn will close the R14b contacts and pick up the R15 and R23 relays.

45 When the Intermediate key 613 is depressed it will pick up the R14 and R22 relays and closure

of the R14b relay contacts will pick up the R15 and R23 relays. Thus, referring to Fig. 37d through this inter-control when the major cam unit control magnet 528 is energized the intermediate 530 and minor 527 magnets will also be energized. When the intermediate cam unit control magnet 530 is energized, the minor cam unit control magnet 527 will also be energized. It will be obvious now that if the control card was perforated in a single row to represent three different fields of the storage unit in which resetting is to be suppressed the above mode of operation could not be secured.

Select skip key 615

The Select skip key 615 is mounted on the keyboard and when operated performs the same functions as the Minor, Intermediate and Major keys except that other columns of the storage unit corresponding to columns in the control card perforated in row 5 may be cleared out and therefore skipped over. The Select skip key 615 will also close its "a" and "b" contacts and the "a" contacts will pick up relays R12 and R20 and the "b" contacts will pick up the R7 relay, and the latter will pick up the R8 relay. R20 relay (Fig. 37d) will close its R20b contacts so as to energize the select skip cam unit control magnet 529. The R8 relay will cause, as described, the energization of the reset cam unit control magnet 460.

Error reset key

The Error reset key 616 is also mounted on the keyboard and its "b" contacts will cause the R7 relay and R8 relay to be energized and under control of the R8 relay the reset cam unit control magnet 460 will be energized, as described. This key is preferably utilized to clear out the storage unit prior to a new setup or in case an error has been made in the setup and it is desired to clear out all previously setup columns. Each time that the space cam unit (see Fig. 32) is actuated it will cause closure of the CU3 cam unit contacts, thereby closing an obvious circuit to the space cam unit control magnet 398. When this cam unit is engaged (see Fig. 32) it causes the reciprocation of the bail 395 to effect a column spacing operation in the storage unit by releasing interposer 379 related to the first column to be set up after an error.

Space magnet circuit controlled by the plurality of error keys 611

As previously described, when each of these keys 611 is operated the Reset keys cam unit (Fig. 32) is actuated which will close contacts CU4 (Fig. 37d) to energize by an obvious circuit the space cam unit control magnet 398, to effect the function above stated.

Space bar and space magnet circuit

As previously stated, column spacing operations are effected by depression of the Space bar 562 which spaces over each column of the storage unit which is not to be set up. Space bar 562 closes contacts 568 (Fig. 37c), closing an obvious circuit through R25b relay contacts and by wire 592 to the space cam unit control magnet 398 (Fig. 32), which latter causes the reciprocation of the bail 395 to effect column spacing. This bail will rock the latch lever 375 of the related column (see Fig. 26) and related segments 345 and 360 will rock to their extreme positions, thus skipping over this column. As previously stated, the cam unit actuated by the space magnet

closes CU2A contacts to energize delay magnet 596, which in turn through its cam unit closes the CU2B contacts to energize trip magnet 597 (Fig. 33) to provide a delay in a keyboard operation which enables segments 345 and 360 to take their extreme rocked positions.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims:

What is claimed is:

1. In a card punching machine, the combination of a magazine for holding a supply of cards, 20 means for successively feeding said cards to a visible station with written data on each card exposed and held to the view of the operator, and thereafter to a punching station, a storage unit including columnar arranged data storage setup 25 means, a keyboard comprising keys operated by the operator according to data written on the card, means controlled by said keyboard to set up said data setup storage means in columnar succession, for representing said written data, card 30 punches of a punching means at said card punching station, and means controlled by said storage unit effective upon completion of the setting up of the data corresponding to matter written on a card to select said punches to punch a data representation on the card in the punching station corresponding to its written data.

2. In a card punching machine, the combination of a magazine for holding a supply of cards, 40 means for successively feeding said cards from said magazine to a visible station with written data on each card exposed and held to the view of the operator, and then feeding the card from said visible station to a punching station, a storage unit including columnar arranged data storage setup means, a keyboard comprising keys operated by the operator according to data written on the card, means controlled by said keyboard to set up said data setup storage means in columnar succession for representing said written data, card 45 punches of a punching means at said card punching station, means controlled by said storage unit effective upon completion of the setting up of the data corresponding to written matter on said card to select said punches to punch a data representation on the card corresponding to its written data, and means for feeding said cards through said punching station for a punching operation.

3. In a card punching machine, the combination of a machine for holding a supply of cards, means for successively feeding each of said cards to a visible station with written data on the card exposed and held to the view of the operator, and 65 concomitantly feeding a succeeding card from the visible station to a punching station, a storage unit including columnar arranged data storage setup means, a keyboard comprising keys operated by the operator according to data written on the card, means controlled by said keyboard to set up said data setup storage means in columnar succession, for representing said written data, card 70 punches of a punching means at said punching station, and means effective upon completion of the setting up of the data corresponding to writ-

ten data on a card to cause the selection of punches under control of said storage setup means to punch a data representation on the card corresponding to the written data, and for feeding the card to be punched through said punching station.

4. In a card punching machine, the combination of a magazine for holding a supply of cards, means for successively feeding each of said cards to a visible station with written data on the card exposed and held to the view of the operator, and concomitantly feeding a succeeding card from the visible station to a punching station, means including a key depressible by the operator for rendering said feeding means effective, a storage unit including columnar arranged data storage setup means, a keyboard comprising keys operated by the operator according to data written on the card, means controlled by said keyboard to set up said data setup storage means in columnar succession, for representing said written data, card punches of a punching means at said punch station, means effective upon completion of the setting up of the data corresponding to a card and when a card has been fed to said punching station to cause the selection of punches under control of said storage setup means to punch a data representation on the card corresponding to its written data, and for feeding the card to be punched through said punching station, and means including a supplemental key depressible by the operator for rendering said last named means effective.

5. In a card punching machine, the combination of a magazine for holding a supply of cards, means for successively feeding each of said cards downwardly to a visible station with written data on the card exposed and held to the view of the operator, and concomitantly feeding a succeeding card farther downwardly from the visible station to a punching station, means including a key depressible by the operator for rendering said feeding means effective, a storage unit including columnar arranged data setup storage setup means, a keyboard comprising keys operated by the operator according to data written on the card, means controlled by said keyboard to set up said data setup storage means in columnar succession, for representing said written data, card punches of a punching means at said punch station, means effective upon completion of the setting up of the data corresponding and when a card has been fed to said punching station to cause the selection of punches under control of said storage setup means to punch a data representation on the card corresponding to its written data, and for feeding the card to be punched still farther downwardly through said punching station, means including a supplemental key depressible by the operator for rendering said last named means effective, a storage hopper, and means for ejecting the punched card into said storage hopper.

6. In a card punching machine, the combination of a magazine for holding a supply of cards, means for successively feeding said cards to a punching station, a storage unit including columnar arranged data storage setup means, a keyboard comprising keys operated by the operator according to data to be punched on the card, means controlled by said keyboard to set up said data setup storage means in columnar succession, means automatically responsive to the setup of the storage setup means pertaining to the last column to be set up, card punches of a punching

means at said punching station, means under control of said data storage setup means to select said punches to punch a data representation on the card corresponding to the keys operated, and means controlled by said responsive means to effect the automatic operation of the preceding means when the last column storage setup means has been set up.

7. In a card punching machine, the combination of a magazine for holding a supply of cards, means for successively feeding said cards from the magazine to a punching station and stopping each card at such station, means for feeding each card through said punching station, a storage unit including columnar arranged storage setup means set up for representing the index point positions on the card, a keyboard comprising keys operated by the operator according to index point positions to be punched on the card, means controlled by said keyboard to set up said setup storage means in columnar succession, means responsive to the setup of the storage setup means pertaining to the last column to be set up, card punches of a punching means at said card punching station, means for reading out said storage setup means as the corresponding index point positions are correlated with the card to select said punches to punch the selected index point positions on the card, means controlled by said responsive means to effect the automatic operation of the preceding means when the last column storage setup means has been set up, and means controlled by said responsive means to cause the operation of the feeding means which feeds the cards from the magazine to feed the next card to said punching station.

8. In a card punching machine, the combination of a magazine for holding a supply of cards, means for successively feeding said cards from the magazine to a punching station and stopping each card at such station, means for feeding each card through said punching station, a storage unit including columnar arranged storage setup means set up for representing the index point positions on the card, a keyboard comprising keys operated by the operator according to the index point positions to be punched on the card, means controlled by said keyboard to set up said data setup storage means in columnar succession, means responsive to the setup of the storage setup means pertaining to the last column to be set up, a card punching means at the card punching station comprising an oscillating means carrying punches and a correlated die which moves the punches and the die with the card to effect card punching while the card is in motion, means for selecting and operating the selected punches, means for reading out said data storage setup means as the corresponding index point positions are correlated with the card to select said punches to punch the selected index point positions on the card while the card is in motion, and means controlled by said responsive means to effect the automatic operation of the preceding means and both of the aforesaid card feeding means when the last column storage setup means has been set up.

9. In a card punching machine, the combination of means for successively feeding said cards to a punching station and then through said punching station to effect punching of the card while in motion in the order 9-1, 0 X, R, a storage unit including columnar arranged storage 0-9, X, R setup means, a keyboard comprising keys operated by the operator according to the index point positions to be punched on the card, means controlled by said keyboard to set up said data setup

storage means in columnar succession, means responsive to the setup of the storage setup means pertaining to the last column to be set up, card punches of a punching means at said punching station for punching cards at selected index point positions while the card is in motion, means for reading out said storage setup means in the order 9-1, 0, X, R as the corresponding index point positions are correlated with the card to select said punches to punch index point positions on the card while the card is in motion, and means controlled by said responsive means to effect the automatic operation of the preceding means and said card feeding means when the last column storage setup means has been set up.

10. In a card punching machine, the combination of means for successively feeding said cards through a card punching station, a storage unit including columnar arranged setup means representing 9-1, 0 X, R, a keyboard comprising keys operated by the operator according to index point positions to be punched on the card, means controlled by said keyboard to set up said data setup storage means in columnar succession, means responsive to the setup of the storage setup means pertaining to the last column to be set up, card punching means at the card punching station including punches for punching a card at selected index point positions while the card is in motion and without stopping the card, means for reading out said storage setup means in the order 9-1, 0, X, R as the corresponding index point positions are correlated with the card to select said punches to punch selected index point positions on the card while the card is in motion, and means controlled by said responsive means to effect the automatic operation of the preceding means and said card feeding means when the last column storage setup means has been set up.

11. In a card punching machine, the combination of a keyboard, a storage unit including columnar arranged data storage setup means, each column having twelve individual setup means, each for representing 9-1, 0 X, R, means controlled by said keyboard to directly set up said setup data storage means in columnar succession to represent alphabetic or numeral data to be punched, card punching means including means for selecting said punches, means for feeding said cards for correlation of said punches and said index point positions in the named order, and means for reading out the setup data representation of said setup storage means in the order 9-1, 0, X, R as the corresponding index point positions are correlated with the punches for causing said punch selecting means to select punches to punch said card to represent the alphabetic or numeral data setup.

12. In a card punching machine, the combination of a keyboard, a storage unit comprising digit bars 0-9 common to a plurality of columns and a differentially settable element for each column which contacts a digit bar to represent a setup in each column, means controlled by said keyboard to effect the differential setting of said contact elements in succession as the keyboard is operated to represent data to be punched, card punching means including electrical means for selecting said punches as said punches are correlated with the rows of index point positions in succession in the order 0-9, means for feeding said cards for correlation of said punches and said index point positions in a certain order, and means for transmitting digit representing impulses to said digit bars in the order 0-9 as the

corresponding index point positions are correlated with the punches for causing, in accordance with the settings of the contact elements of all the columns, said electrical punch selecting means to select punches to punch said card to represent setup data in the storage unit.

13. In a card punching machine, the combination of a keyboard, a storage unit including columnar arranged data storage setup means for setting up in one portion a representation of 9-1, and in another separate portion a 0, X, R representation, means controlled by said keyboard to set up said setup data storage means in columnar succession to represent data to be punched, card punching means including means for selecting said punches as said punches are correlated with the rows of index point positions in succession in the order 9-1, 0 X, R, means for feeding said cards for correlation of said punches and said index point positions in the named order, means for reading out the 9-1 portion and then 0, X, R portion of the storage unit in the named order as corresponding index points are correlated with said punches for causing said punch selecting means to be controlled first by one portion of the storage unit and then the other portion to select punches to punch 9-1 index points of the card, and then 0, X, R index points of the card.

14. In a card punching machine, the combination of a keyboard, a single storage unit including columnar arranged data storage setup means having in each column ten individual setup means for representing 9-0, means controlled by said keyboard to set up said setup data storage means in columnar succession to represent data to be punched, card punching means including means for selecting said punches, means for feeding said cards for correlation of said punches and said index point positions in the order 9-0, means for reading out the data setup means of said storage unit set up by said keyboard in the order 9-0 as the corresponding index point positions are correlated with the punches for causing said punch selecting means to select punches to punch said card to represent setup data.

15. In a card punching machine, the combination of a keyboard, a storage unit including columnar arranged data storage setup means for representing 9-0, means controlled by said keyboard to set up said setup data storage means in succession to represent data to be punched, card punching means comprising oscillating means carrying punches and a correlated die, said punches and die in one direction moving with the card at the same rate the card is being fed for effecting card punching without stopping the card, means for feeding said cards for correlation of said punches and said index point positions, means for selecting and operating said punches, and means for reading out the setup data representation of said setup storage means as the corresponding index point positions are correlated with said punches for causing said punch selecting means to select punches to punch said card to represent setup data while the card is in motion and without requiring the card to be stopped for punching operation at any index point position.

16. In a machine for gang punching the same data on successive cards, the combination of a supply magazine, a keyboard, a storage unit including columnar setup storage means set up to represent index point positions to be punched, means controlled by said keyboard for setting up

said setup means in columnar succession as the keyboard is operated, means for feeding cards successively from said supply magazine to and through a card punching station, card punching means including punches at said punching station, means for cyclically reading out said storage setup means once for each card to be punched for selecting said punches to punch index point positions corresponding to the storage means set up, means responsive to the position of a card at said card punching station, and means controlled by said last named means to effect continuous operations of said feeding means and said cyclically operable reading out means for a group of cards which are fed to the punching station to be punched alike.

17. In a machine for gang punching the same data on successive cards, the combination of a supply magazine, a keyboard, a storage unit including columnar setup storage means set up to represent index point positions to be punched, means controlled by said keyboard for setting up said setup means in columnar succession as the keyboard is operated, means for feeding cards successively from said supply magazine to and through a card punching station, card punching means including punches at said punching station, means for cyclically reading out said storage setup means once for each card to be punched for selecting said punches to punch index point positions corresponding to the storage means set up, and means to effect continuous operations of said feeding means and the cyclically operable reading out means as long as cards are fed to the punching station which are to be punched alike.

18. In a machine for gang punching the same data on successive cards, the combination of a supply magazine, a keyboard, a storage unit including columnar setup storage means set up to represent index point positions to be punched, means controlled by said keyboard for setting up said setup means in columnar succession as the keyboard is operated, which setup is retained until a clearing operation is effected, means for clearing out the setup of said storage setup means, means for feeding cards successively from said supply magazine to and through a card punching station, card punching means including punches at said punching station, means for cyclically reading out said storage setup means once for each card to be punched for selecting said punches to punch index point positions corresponding to the storage means set up, means to effect continuous operations of said feeding means and said cyclically operable reading out means for a group of cards which are fed to the punching station to be punched alike, and means including selective means settable by the operator for rendering said clearing out means operable when a group of cards has been punched.

19. In a machine for gang punching the same data on successive cards, the combination of a supply magazine, a keyboard, a storage unit including columnar setup storage means individually set up to represent the index point positions to be punched, means controlled by said keyboard for setting up said setup means in columnar succession as the keyboard is operated, means for feeding cards successively from said supply magazine to and through a card punching station, card punching means at the card punching station including punches for punching the index point positions while the card is in motion and without stopping the card, means for cyclically reading out said storage setup means as the index points

represented by the card pass the card punches for effecting the operation of said punches to punch index point positions corresponding to the storage means set up, in each column, and means to effect continuous operations of said feeding means and said cyclically operable reading out means for each card of a group of cards fed to the punching station to be punched alike.

20. In a machine for gang punching the same data on successive cards, the combination of a supply magazine, a keyboard, a storage unit including in each column a plurality of setup means set up to store and represent the 9-1, 0, X, R index point positions to be punched, means controlled by said keyboard for setting up said setup means in columnar succession as the keyboard is operated, means for feeding cards successively from said supply magazine to and through a card punching station, card punching means at said punching station comprising oscillatable means carrying punches, punch operating means and a correlated die which moves with the die at the same rate as the card is fed to effect punching of the card while the card is in motion and without stopping the card, means for cyclically reading out said setup means in the order 9-1, 0, X, R as the corresponding index points are correlated with said punches for selecting and operating said punches to punch the index point positions while the card is in motion, and means to effect the continuous operations of said feeding means and said cyclically operable reading out means for each card of a group of cards fed to the punching station to be punched alike.

21. In a card punching machine, the combination of means for successively feeding each of a series of cards through a punching station, a storage unit including columnar-arranged data storage setup means, a keyboard, means under control of the keyboard to set up said data storage setup means, means for reading out said storage setup means, means for reading out a plurality of columns of master card perforations, means responsive to the setup of the setup means pertaining to the last column set up, card punches of a punching means at said card punching station, and means controlled by said responsive means to effect the automatic operation of the card feeding means, said storage setup reading out means, and said master card perforation reading out means to cause the selection of punches conjointly under control of the master card and storage setup means.

22. In a card punching machine, the combination of means for successively feeding cards through a punching station, a storage unit including columnar-arranged data storage setup means representing the index point positions 9-1, 0, X, R, a keyboard, means under control of the keyboard to set up said data storage setup means, means for reading out said storage setup means in the order 9-1, 0, X, R, means for reading out a plurality of columns of master card perforations in the order 9-1, 0, X, R, means responsive to the setup of the setup means pertaining to the last column set up, card punches of a punching means at said card punching station, and means controlled by said responsive means to effect the automatic operation of said storage setup reading out means, said master card perforation reading out means, and said card feeding means to correlate the index point positions with the punches in the same order that the master and perforations and storage setup means are read out to effect the selection of punches

conjointly under control of the master card and storage setup means.

23. In a card punching machine, the combination of means for feeding a card to a visible reading station, where it is held for exposure of written data thereon, a storage unit including columnar arranged data storage setup means, a keyboard, means under control of the keyboard which is operated according to the written data to set up said data storage setup means, means for reading out said storage setup means, means for reading out columns of master card perforations, means for feeding a card to be punched from the visible station through said punching station, card punches of a punching means at said card punching station, and means operable when said storage unit has been set up to effect the operation of the last named card feeding means, said storage setup reading out means, and said master card perforation reading out means to cause the selection of punches conjointly under control of the master card and storage setup means.

24. In a machine for gang punching the same data on successive cards, the combination of a supply magazine, a keyboard, a storage unit including columnar setup storage means set up to represent index point positions to be punched, means controlled by said keyboard for setting up said setup means in columnar succession as the keyboard is operated, means for feeding cards successively from said supply magazine to and through a card punching station, means for reading out a plurality of columns of a master card, means for reading out said setup storage means, card punching means including punches at said punching station, means for effecting the operation of said storage setup reading out means and said master card reading out means once for each card to be punched for selecting said punches to punch index point positions corresponding to the storage means set up, means responsive to the position of a card at said card punching station, and means controlled by said last named means to effect continuous operations of said card feeding means and both of said reading out means as long as cards are fed to the punching station which are to be punched alike according to data represented on both the master card and storage unit.

25. In a machine for duplicating data represented on a perforated master card, the combination of a series of columnar-arranged master card analyzing brushes, means to reciprocate said master card relatively to said brushes, means to effect an operative relationship between the master card and said analyzing brushes to analyze the rows of the master card index point positions in the order 9-1, 0, X, R, card punching means, means to feed a card to be punched to correlate the card punching means with the index points of said card in the order 9-1, 0, X, R synchronously with the analysis of the corresponding master card index point positions, and means controlled by the master card analyzing brushes to select the punches for operation to duplicate master card perforated data on the card to be punched.

26. In a machine which can be selectively conditioned to effect gang punching of common data for a series of cards, or to punch each card with individually setup data, the combination of a storage unit including columnar setup storage means, a keyboard, means under control of said keyboard to effect the setup of said storage setup

means to represent data to be punched, card punching means at a punching station including punches, means for reading out said storage setup means for selecting said punches to punch the cards to represent data set up on said storage unit, means for feeding said cards through said card punching station, alternatively set means comprising means set when gang punching operations are to be effected to cause continuous card feeding and reading out operations for punching a series of cards alike and other means operable when individual card punching is to be effected to cause only a single operation of said readout means and card feeding means for each card fed for punching each card to represent the individual data set up on said storage unit, and means for clearing out said storage setup means after punching each card to represent individual data.

27. In a machine which can be selectively arranged to effect gang punching of common data for a series of cards, or to punch each card with individually setup data, the combination of a storage unit including columnar setup storage means, a keyboard, means under control of said keyboard to effect the setup of said storage setup means to represent data to be punched, card punching means at a punching station including punches, means for reading out said storage setup means for selecting said punches to punch the cards to represent data set up on said storage unit, means for feeding said cards through said card punching station, means responsive to the last column set up in said storage unit, alternatively set means comprising means set when gang punching operations are to be effected to cause continuous card feeding and reading out operations for punching a series of cards alike, and other means automatically set into operation by said responsive means when the last column of the storage unit is set up to cause, when individual card punching is to be effected, only a single operation of said readout means and card feeding means for each card fed for punching each card to represent the individual data set up on said storage unit, and means for clearing out said storage setup means after punching each card to represent individual data.

28. In combination with the arrangement defined in the preceding claim 27, a master card analyzing unit, means under control of said analyzing unit to control said card punching means to duplicate data on cards to be punched, and means controlled by said alternatively set means and said other means to cause said master card analyzing unit to be operated for each card punching operation to effect duplication of data on each card, whether the machine is conditioned for gang punching or individual card punching.

29. In a machine which can be selectively conditioned to effect punching of data for a series of cards in two different modes of operation, the combination of a card supply magazine, means for feeding each card from said supply magazine to a visible station where it may be held exposed for written data thereon, a key to initiate operation of said feeding means, a storage unit including columnar setup storage means, a keyboard, means under control of said keyboard to effect the setup of said storage setup means to represent data to be punched on each card and in one mode of operation to correspond with data written on the card, card punching means at a punching station including punches, means for reading out said storage setup means for selecting

said punches to punch the cards to represent data set up on said storage unit, means for feeding said cards from said visible station through said card punching station, a key to initiate operation of said preceding card feeding means, alternatively set means comprising means set when punching operations are to be effected according to written data to cause, by the operation of said first key, the feeding of each card from the supply magazine to the visible station and to be held exposed there while the storage unit is set up, and by said second key to cause the operation of said second named card feeding means and said reading out means after setting up the storage unit to punch each card according to the written data thereon, and other means operable when punching operations are to be effected according to the other mode of operation to cause, after setting up the storage unit, the operation of both of said card feeding means concurrently with the operation of the reading out means to cause each card to be punched to represent data set up on said storage unit, and means for clearing out said storage setup means after punching each card in either mode of operation.

30. In a machine which can be selectively conditioned to effect punching of data for a series of cards in two different modes of operation, the combination of a card supply magazine, means for feeding each card from said supply magazine to a visible station where it may be held exposed for written data thereon, a key to initiate operation of said feeding means, a storage unit including columnar setup storage means, a keyboard, means under control of said keyboard to effect the setup of said storage setup means to represent data to be punched and in one mode of operation to correspond with data written on the card, means responsive to the setup of the setup storage means of the last column set up, card punching means at a punching station including punches, means for reading out said storage setup means for selecting said punches to punch the cards to represent data set up on said storage unit, means for feeding said cards from said visible station through said card punching station, a key to initiate operation of said preceding card feeding means, alternatively set means comprising means set when punching operations are to be effected according to written data to cause, by the operation of said first named operation of said first named card feeding means to effect the feeding of each card from the supply magazine to the visible station and to be held exposed there while the storage unit is set up, and by said second named key to cause the operation of said second named card feeding means and said reading out means after setting up the storage unit to punch each card according to the written data thereon, and other means operable when punching operations are to be effected according to the other mode of operation to cause said responsive means when the last column is set up the initiation of the operation of both of said card feeding means concurrently with the operation of the reading out means to cause each card to be punched to represent data set up on said storage unit, and means for clearing out said storage setup means after punching each card in either mode of operation.

31. In a machine which can be selectively arranged to effect gang punching of common data for a series of cards, or to punch each card with individually setup data corresponding to the data written on the card, the combination of

a means for feeding each card of a series from a supply magazine to a visible station where it is held exposed for written matter thereon, a storage unit including columnar setup storage means, a keyboard, means under control of said keyboard to effect the setup of said storage setup means to represent data to be punched, card punching means at a punching station including punches, means for reading out said storage setup means for selecting said punches to punch the cards to represent data set up on said storage unit, means for feeding said cards from said visible station through said card punching station, alternatively set means comprising means set when gang punching operations are to be effected to cause continuous operations of both of said card feeding means and said reading out means for punching a series of cards alike under control of said storage unit, and other means operable when card punching is to be effected according to the data written thereon to cause the operation of said first named feeding means prior to the setting up of the storage unit, and to cause after setting up of the storage unit the operation of said second named card feeding means and said reading out means to punch each card to correspond with the data written thereon, and means for clearing out said storage setup means after punching each card according to the last described mode of operation.

32. In a machine which can be selectively conditioned to effect punching of data for a series of cards, by gang punching a series of cards, by punching each card to represent data written thereon, or by punching each card to represent certain other data, the combination of means for feeding each card from a supply magazine to a visible station where it may be held exposed for written data thereon, a key to initiate the operation of said feeding means in one mode of operation, a storage unit including columnar setup storage means, a keyboard, means under control of said keyboard to effect the setup of said storage setup means to represent data to be punched on each card, which data is common for a series of cards in gang punching, and in one mode of operation corresponds to data written on the card, card punching means at a punching station including card punches, means for reading out said storage setup means for selecting said punches to punch cards to represent data setup on the storage unit, means for feeding each card from the visible station through said card punching station, settable means for conditioning the machine according to the three modes of operation comprising means set when gang punching operations are to be effected to cause continuous operations of both of said feeding means and said reading out means for punching under control of said storage unit a series of cards to represent common data, other means operable when card punching is to be effected according to the data written on a card to cause the operation of said first named feeding by said key to hold the card at the visible station prior to the setting up of the storage unit, and to cause after setting up of the storage unit the operation of said second named card feeding means and said reading out means to punch each card to correspond with the data written thereon, and still other means operable when punching operations are to be effected according to the third mode of operation to cause, after setting up the storage unit, the operation of both of said card feeding means concurrently

with the operation of the reading out means to cause each card to be punched to represent said certain data set up on said storage unit, and means for clearing out said storage setup means after punching each card according to the last two described modes of operation.

33. In a data storage setup arrangement for controlling card punching, the combination of a storage unit for controlling punching means including columnar arranged data storage setup means, arranged in divisions, each division comprising a plurality of columns, a keyboard, means controlled by said keyboard to set up said data storage setup means in columnar succession as the keyboard is operated, a plurality of clearing means, one for each column, a plurality of error correcting keys, one for each division, and means controlled by each key for causing the operation of the clearing means of a plurality of columns comprising an associated division of the storage unit which includes the column in which an error in setup of the setup means has been detected.

34. In a data storage setup arrangement for controlling card punching, the combination of a storage unit for controlling a punching means including columnar arranged data storage setup means, arranged in divisions, each division comprising a plurality of columns, a keyboard, means controlled by said keyboard to set up said data storage setup means in columnar succession as the keyboard is operated, a plurality of clearing means, one for each column, a plurality of means each to effect the operation of said clearing means for a plurality of columns, a plurality of error correcting keys, one for each division, means controlled by said error correcting keys to cause the operation of the related operating means for clearing of a division of the storage unit which includes the column in which an error in setup of the setup means has been detected, and means to effect the simultaneous operation of a plurality of clearing means at the completion of a card punching operation to clear out all columns of the storage unit.

35. In a data storage setup arrangement for controlling card punching, the combination of a storage unit for controlling card punching including columnar arranged data storage setup means, arranged in divisions, each division comprising a plurality of columns, and each column of the setup means comprising a differentially set contact element for contact with a plurality of index point representing bars, according to the index point to be punched, a keyboard, means controlled by said keyboard to release said contact elements in columnar succession to differential positions as the keyboard is operated, a plurality of clearing means, one for each column for resetting said contact elements from their differential positions, a plurality of means each to effect the operation of said clearing means for a plurality of columns, a plurality of error correcting keys, one for each division, and means controlled by each of said keys for causing the operation of the related operating means to cause the resetting of the contact elements in the columns of a division of a storage unit which includes the column in which an error in setup of the setup means has been detected.

36. In a data storage setup arrangement for controlling card punching, the combination of a storage unit for controlling card punching including columnar arranged data storage setup means, arranged in divisions, each division com-

prising a plurality of columns, and each column of the setup means comprising a differentially set contact element for contact with a plurality of index point representing bars, according to the index point to be punched, a keyboard, means controlled by said keyboard to release said contact elements in columnar succession to differential positions as the keyboard is operated, a plurality of clearing means, one for each column for resetting said contact elements from their differential positions, a plurality of means each to effect the operation of said clearing means for a plurality of columns, a plurality of error correcting keys, one for each division, means controlled by each of said keys for causing the operation of the related operating means to cause the resetting of the contact elements in the columns of a division of the storage unit which includes the column in which an error in setup of the setup means has been detected, and means to effect the simultaneous operation of a plurality of clearing means at the completion of a plurality punching operation to reset the contact elements of all columns of the storage unit.

37. In a data storage setup arrangement for controlling card punching, the combination of a storage unit including columnar arranged data storage setup means, arranged in divisions, each division comprising a plurality of columns, a keyboard, means controlled by said keyboard to set up said data storage setup means in columnar succession as the keyboard is operated, a plurality of clearing means, one for each column, a plurality of error correcting keys, one for each division, means controlled by said error correcting keys to cause the clearing of a plurality of columns comprising an associated division of the storage unit which includes the column in which an error in setup of the setup means has been detected, and means including either a manually operated key or means automatically operable at the completion of a card punching operation to effect the operation of the plurality of clearing means for all the columns of the storage unit.

38. In a card punching machine, the combination of a keyboard, a storage unit including columnar setup means set up to represent variable and invariable data to be punched on a card, means under control of said keyboard to effect the invariable and variable data set up on said storage unit, clearing means operable at the completion of each card punching operation for normally attempting to reset or clear out all the columns of the storage unit representing the variable and invariable data, a perforated control card, and means controlled by the perforations of said control card to suppress the clearing out of one or more columns of the storage unit corresponding to the columns of the control card which are perforated, whereby the corresponding setup means are retained set up to represent invariable data to be punched on a series of cards.

39. In a card punching machine, the combination of a keyboard, a storage unit including columnar setup means set up to represent variable and invariable data to be punched on a card, means under control of said keyboard to effect the setup of said setup means in columnar succession as the keyboard is operated to effect invariable and variable data on said storage unit, column spacing means to effect the setup in columnar succession, clearing means operable at the completion of each card punching operation for normally attempting to reset or clear out all the columns of the storage unit representing the vari-

able and invariable data, a perforated control card, and means controlled by the perforations of said control card to suppress the clearing out of one or more columns of the storage unit corresponding to the columns of the control card which are perforated, and to condition the spacing means to cause a setup by a keyboard operation to be diverted to the next column to be set up and skipped over columns which are retained set up, whereby the corresponding setup means are retained set up to represent invariable data to be punched on a series of cards, and no keyboard operations are required for columns representing invariable data which are retained set up.

40. In a card punching machine, the combination of a keyboard, a storage unit including columnar setup means set up to represent variable and invariable data to be punched on a card, means under control of said keyboard to effect the variable data set up on said storage unit, and the invariable data set up in a plurality of divisions, each comprising a plurality of columns, clearing means operable at the completion of each card punching operation for normally attempting to reset or clear out all the columns of the storage unit representing the variable and invariable data, a perforated control card, perforated in a plurality of columns, and in different rows, and means controlled by each row of perforations of said control card to suppress the clearing out of the related division of the storage unit and in columns corresponding to the columns of the control card which are perforated in that row, whereby the corresponding setup means of that division are retained set up to represent invariable data to be punched on a series of cards.

41. In a card punching machine, the combination of a keyboard, a storage unit including columnar setup means set up to represent invariable data to be punched on a series of cards, means under control of said keyboard to effect the invariable data set up on said storage unit, clearing means normally operable at the completion of each card punching operation for attempting to reset or clear out all the columns of the storage unit representing the invariable data, a control card, and means controlled by the control card to suppress the clearing out of one or more columns of the storage unit corresponding to the columns of the control card which are perforated, whereby the corresponding setup means are retained set up to represent invariable data to be punched on a series of cards.

42. In a card punching machine, the combination of a keyboard, a storage unit including columnar setup storage means set up to represent data to be punched on a card, means under control of said keyboard to effect the data set up on the setup means of said storage unit, which setup means is normally cleared out at the completion of each card punching operation, a perforated control card, and means controlled by the perforations of said control card to suppress the clearing out of one or more columns of the storage unit corresponding to the columns of the control card which are perforated, whereby the corresponding setup means are retained set up to represent invariable data to be punched on a series of cards.

43. In a card punching machine, the combination of a keyboard, a storage unit including columnar setup means set up to represent variable and invariable data to be punched on a card, means under control of said keyboard to effect the data set up on said setup means in columnar

succession, which setup means for certain columns are retained set up for punching a plurality of cards with invariable data, column spacing means operable by each keyboard operation to cause the setups to be effected in columnar sequence, a perforated control card, and means controlled by the perforations of said control card to suppress the clearing out of one or more columns of the storage unit corresponding to the columns of the control card which are perforated and to condition the spacing means to divert in the following keyboard operation a setup to the next column to be set up and skip over said certain columns which are retained set up, whereby said certain columns are retained set up to represent invariable data to be punched on a series of cards, and no keyboard operations are required for spacing over columns which are retained set up.

44. In a card punching machine, the combination of a keyboard, a storage unit including columnar setup means set up to represent variable and invariable data to be punched on a card, means under control of said keyboard to effect the setup of said setup means in columnar succession as the keyboard is operated to effect the setup of invariable and variable data on said storage unit, column spacing means to effect the setups in columnar succession, and means to suppress the clearing out of one or more columns of the storage unit corresponding to the columns which are to represent invariable data and to condition the spacing means to cause a setup by the next keyboard operation to be diverted to the next column to be set up and skipped over column which are retained set up, whereby the corresponding setup means are retained set up to represent invariable data to be punched on a series of cards, and no keyboard operations, not even space bar operations, are required for spacing over columns representing invariable data which are retained set up.

45. In a card punching machine, the combination of a storage unit including columnar setup means arranged in two divisions, each division comprising a plurality of columns, to represent classification data of different ranks to be punched on a series of cards, means for setting up said setup means to represent the ranked data in the two divisions of the storage unit, reset or clearing keys, one for each division, means controlled by each key for clearing out the setup means of the related division, and further means controlled by the key related to the division having a higher rank for clearing out the setup means of the other division lower in rank.

46. In a card punching machine, the combination of a storage unit including columnar setup means set up in two divisions, each division comprising a plurality of columns, to represent classification data of two different ranks to be punched on a series of cards, means for setting up said setup means to represent the ranked data in two different divisions of the storage unit, two reset or clearing keys, one for each division and each to effect the clearing out of the related division, and means controlled by the key of higher rank for clearing out the setup means of the other division which is lower in rank.

47. In a card punching machine, the combination of a storage unit including columnar setup means arranged in a plurality of divisions exceeding two, each division comprising a plurality of columns, to represent classification data of different ranks to be punched on a series of cards, means for setting up said setup means to repre-

sent the ranked data in different divisions of the storage unit, a plurality of reset or clearing keys, one for each division, means controlled by each key for clearing out the setup means of the associated division, and means controlled by each reset key of higher rank for also clearing out the setup means of one or more divisions which are lower in rank.

48. In a card punching machine, the combination of a storage unit including columnar setup means set up in a plurality of divisions, each division comprising a plurality of columns, to represent in order of rank, higher to lower, major, intermediate and minor group control data to be punched on a series of cards, means for setting up said setup means to represent the ranked data in different divisions of the storage unit, a major, intermediate and minor clearing or reset key, means controlled by each key for clearing out the division representing the related major group control data, and means controlled by the major key for clearing out the setup means of the divisions representing intermediate and minor group control data, and controlled by the intermediate key for clearing out the setup means of the division representing minor group control data.

49. In a card punching machine, the combination of a storage unit including columnar setup means set up in a plurality of divisions, each division comprising a plurality of columns, to represent classification data of different ranks to be punched on a series of cards, means for setting up said setup means to represent the ranked data in different divisions of the storage unit, a perforated control card, means for attempting to clear out the setup means of all columns comprising all divisions at the completion of a card punching operation, means under control of the control card to suppress the clearing out of columns of the storage unit corresponding to perforated columns of the card, whereby one or more divisions of the storage unit may be retained set up, a plurality of clearing or reset keys, one for each division, means controlled by each key for causing the clearing out of the related subdivision when the control card has prevented the clearing out of that division, and means controlled by each key related to a division having a higher rank for clearing out the setup means of each division which is lower in rank, if said control card has prevented the clearing out of such divisions of lower rank.

50. In a card punching machine, the combination of a storage unit including columnar setup storage means set up to represent data to be punched on a card, means to effect the data set up on the setup means of said storage unit, means for clearing out the setup means at the completion of a card punching operation, a perforated control card, means controlled by the perforations of said control card to suppress clearing out of the columns of the storage setup means corresponding to the columns of the control card which are perforated, whereby the corresponding setup means are retained set up to represent invariable data to be punched on a series of cards, a reset or clearing key, and means controlled by said key for causing the clearing out of the columns of the storage setup means when the control card has prevented the clearing out of said columns at the completion of the card punching operation.

51. In a machine for analyzing data on a master card or the like, the combination of a fixed plate on which said card is placed, a pair of reciprocable

carriage blocks disposed at each side of said fixed plate, a plurality of grippers carried by each block for gripping two of the edges of the card against each block, means for actuating said grippers after the initial movement of said carriage blocks, and spring-operated means arranged to follow the movement of the card carriage blocks for moving the card over said fixed plate prior to actuation of said grippers to gripping position.

52. In a machine for analyzing data on a master card or the like, the combination of analyzing brushes, a reciprocable card carriage, a plurality of grippers carried by said carriage for gripping two of the edges of the card, means for actuating said grippers after the initial movement of said carriage, and spring-operated card picker means arranged to follow the movement of the card carriage for moving the card past said analyzing brushes prior to actuation of said grippers to gripping position.

53. In a machine for analyzing data on a master card or the like, the combination of a fixed plate on which said card is placed, a series of analyzing brushes, a coordinated contact roller engaged by said brushes through the card perforations, means arranged at each side of said fixed plate for gripping two of the marginal edges of the card and for moving said card off said fixed plate, past said analyzing brushes, and then returning said card upon said fixed plate, and means to effect an operative relationship between said brushes and contact roller during the movement of the card past said analyzing brushes, and to effect a relative separation between said analyzing brushes and contact roller during the return movement of said card.

54. In a machine in which card punching means are provided to successively punch data derived from one or more different sources, the combination of a supply magazine, means for feeding each card vertically downward from said supply magazine to a visible reading station in one cyclic operation where said card may be exposed for examination of written data, then in a subsequent cyclic operation move the card farther downwardly to said card punching means at said punching station, further card feeding means to feed each card still farther downwardly through said punching station to an eject position, means for sensing the eject position of said punched card, means for feeding said card traversely from said eject position to a storage position, and means controlled by said sensing means for causing the operation of said last named feeding means to feed a punched card traversely to a storage position.

55. In a machine in which card punching means are provided to successively punch data derived from one or more different sources, the combination of a supply magazine, means for feeding each card vertically downward from said supply magazine to a visible reading station in one cyclic operation where said card may be exposed for examination of written data, then in a subsequent cyclic operation move the card farther downwardly to said card punching means at said punching station, further card feeding means to feed each card still farther downwardly through said punching station to an eject position, means for sensing the eject position of said punched card, means for feeding said card traversely from said eject position to a storage position, means controlled by said sensing means for causing the operation of said last named feeding means to feed a punched card traversely to a storage position in front of

the machine, a storage hopper, and means in said storage hopper for projecting said cards in said hopper in upright stacked position in front of the machine and with the last card fed thereto out of the path of the incoming next card.

56. In a machine for punching cards at selected index point positions and at exact locations thereof, the combination of pairs of feeding rollers for feeding a card to be punched, fixed stops associated with one pair of feeding rollers against which the leading edge of a card projects when said trailing edge is free of the other pair of rollers, spring operated means engageable with the trailing edge of the card to project the leading edge of the card against said fixed stops to align the card along the horizontal edges, further spring-operated means cooperating with the side marginal edges of the card to align the card along said marginal edges, and means for separating

the pair of rollers cooperating with the leading edge of the card before the operation of both of said spring-operated means.
